UNITED STATES PATENT OFFICE.

WILLIAM L. DODGE, OF MAPLEWOOD, AND JOHN B. RETALLACK, OF EAST ORANGE, NEW JERSEY, ASSIGNORS TO WESTERN ELECTRIC COMPANY, INCORPORATED, OF NEW YORK, N. Y., A CORPORATION OF NEW YORK.

TESTING SYSTEM FOR TESTING SENDERS OF AUTOMATIC TELEPHONE EXCHANGES.

Application filed September 29, 1924. Serial No. 740,446.

To all whom it may concern:

Be it known that we, WILLIAM L. DODGE and JOHN B. RETALLACK, citizens of the United States of America, residing at

5 Maplewood and East Orange, in the county of Essex and State of New Jersey, respectively, have invented certain new and useful Improvements in Testing Systems for Testing Senders of Automatic Telephone 10 Exchanges, of which the following is a full, clear, concise, and exact description.

This invention relates to telephone exchange systems and more particularly to a testing arrangement for use in a machine switching system for testing register senders.

Since register senders for use in machine switching systems vary according to the type of line with which they are to be used; that is whether or not the subscriber is required 20 to deposit a coin in order to complete connections, it is obvious that a sender testing arrangement designed for testing senders used with coin-lines, must be adapted to test the ability of the sender to test whether a 25 coin has been deposited, and to collect or refund the coin according to whether the connection is completed or not. A testing system for testing a sender used with non-coin lines has been disclosed and claimed 30 in patent to William L. Dodge No. 1,523,408, granted January 20, 1925.

It is an object of the present invention to provide a testing system for senders; and particularly senders used with coin-lines.

35 A feature of the invention is the provision of means to test either coin senders or non-coin senders with tests individual to each.

Another feature of the invention is the provision of means for simulating various 40 coin conditions and for checking the response of the sender thereto.

Still another feature of the invention is the provision of means for delaying the simulation of coin deposit to test the sender 45 for its ability to block a call when no coin is deposited.

An additional feature of the invention lies in the provision of means for repeatedly dismissing and reselecting a sender and applying coin collect or refund current, to test the ability of the sender to respond to various conditions of the line when it tests the line after coin collect or refund.

A further feature of the invention lies

in means for repeating the coin test at will. 55

A still further feature lies in the provision of means for repeating single tests a plurality of times on each sender.

Referring to the drawings, Figs. 1 to 14, and Figs. 25 to 27, inclusive, when arranged in accordance with the diagram illustrated in Fig. 28 disclose in detail the circuits and apparatus of the testing device embodying the principles of the present invention. 65

Fig. 15 shows master selectors and sender selectors for connecting the testing device with a large number of senders.

Figs. 16 and 18 to 24, inclusive, when arranged in the order illustrated by the aforesaid diagram show in detail the circuits of an office sender of the type employed with non-coin lines. 70

Figs. 17 to 24, inclusive, when arranged in the order shown in Fig. 28 show the 75 circuits and apparatus of a sender of the type employed with coin lines.

The apparatus included in this testing set is of well known types and consists of sequence switches and step-by-step switches 80 which have been frequently employed in the art and are described in detail in the above mentioned application to Frank N. Reeves, Serial No. 678,944, filed December 6, 1923. The sender shown in Figs. 16 to 24, inclusive, is of the type shown in patent to Ottmar H. Kopp, No. 1,509,484, issued September 23, 1924. For illustration of the functioning of the sender in the testing for, collection and refund of a coin, reference is 85 made to U. S. Patent to Ellis H. Mills, No. 1,504,261, granted August 12, 1924. 90

General description and operation.

Before proceeding with the description of 95 the operation involved in the routine testing of a group of senders, it is believed that a general description of the operation of the testing device and sender will assist in an understanding of the details which follow. 100 The senders in an office of the machine switching type are usually mounted on one or more frames together with selector switches. The routine testing device which is the subject-matter of this invention is 105 located on adjacent frames with the lamps and control keys positioned on a suitable desk.

Assuming that the apparatus of the testing device is in its normal position, a routine test of the senders in an office is started by the actuation of start key 1401. The operation of various relays follows the actuation of the start key, and the sequence switch 1400 rotates to establish a sequence of circuits to position the switches for the test. The master switches 1500 and 1510 are associated with group switches 1520, 1530 and 1540. The terminals associated with the brushes of switch 1520, connect to the first twenty senders to be tested. The terminals of switches 1530 and 1540 also connect with twenty or less senders. Switches 1520 and 1530 are connected to senders employed with non-coin lines while switch 1540 is represented as connected to senders employed with coin lines. The master switches 1500 and 1510 and switch 1520 are positioned to bring the testing device into association with the first sender to be tested.

This sender is now tested to ascertain whether it is busy or idle. If it is idle the testing device renders it busy so that it cannot be seized by a district selector switch. If it is busy the testing device waits until it becomes idle.

The route control switch of Fig. 13 is now positioned in accordance with the first test to be made. The register switches are then positioned in accordance with the setting of the route control switch.

When all the register switches have been positioned either interrupter 700 or interrupter 750 is operated to send impulses to the sender to position the registers of the sender.

Interrupter 700 is driven by accurately timed mechanism to rotate it to simulate the slowest possible dial interruptions which are ordinarily received by the sender mechanism from a subscriber's dial. Interrupter 750 is controlled accurately to simulate the most rapid interruptions received from a subscriber's station dial. During the automatic routine test, interrupter 750 is employed during the first test of the sender. Upon each revolution of interrupter 750 a series of interruptions is transmitted to the sender to set one register in the manner that it would be set from a subscriber's station dial. Cam 701 of the interrupter is arranged to release the pulsing relay 1900 ten times upon each revolution of the ten insulated segments. The interruptions at each revolution of the interrupter are regulated by a shunt circuit through the cams of the various register switches and numerical switches shown in Figs. 6, 7, 9 and 10. Therefore, the number of interruptions transmitted is controlled both by interrupter 750 and a cam of a register switch.

The first register of the sender to be positioned through the rotation of interrupter

750 and the cam contacts of register 645 is the A code register 2103. The second register of the sender to be set is the B code register 2110. This is also set in accordance with the interruptions of the circuit of the pulsing relay 1700 caused by interrupter 750 supplemented by cam contacts of the B code register switch 660. The setting of the A and B register switches in the sender controls the translator to position it for district brush, district group, office brush and office group selections.

When the sender registers have been positioned, a fundamental circuit is established between the testing set and the sender similar to that employed in the control of selector switches by the sender. The testing device provides means for shunting the stepping relay of the sender in a manner similar to the commutator of a selector switch and for operating the counting relays of the sender. At the same time the counting relays of the testing device are operated and when the zero group of counting relays in the sender opens the above fundamental circuit, at the end of the first selection control by the sender, a circuit is prepared for advancing the testing device to a position for checking the next selection provided the correct number of counting relays have been operated in the testing device.

A plurality of tests are usually made on each sender by the operation of key 1101 and at the completion of each test means are provided for resetting the route control switch 1300 to control the next test.

Test No. 1 includes the setting of station registers to simulate the routing of a call through an office other than the one at which the call is initiated. The second test to be made sets the code and numerical registers without stations, to route a call to a subscriber's station in the machine switching office initiating the call. This is made in a similar manner to that described with the exception of the station registers of the sender. One of the tests included in the multiple test which differs from the ordinary machine switching control is the control of the sender for a call to a relay call indicator office. For this type of test the registers are set in a similar manner to that described, with the exception that the register switches of the testing device are differently positioned by the route control and the numerical switches shown in Figs. 12 and 13. The registers of the sender are thus positioned to operate the relay call indicator apparatus in a distant manual office and the translator is positioned to route the district and office selector switches to a relay call indicator trunk. The operation of the testing device to check the district brush, district group, office brush and office group selections is the same as previously de-

scribed. Upon the completion of the office group selection, the fundamental circuit is transferred to the relay call indicator apparatus shown in Figs. 2, 25, 26 and 27 to control relay call indicator apparatus from the sender. The pulsing switch shown in Fig. 24 is actuated to transmit various pulses to the polarized relays 2517 and 2518 and relay 2519 of the relay call indicator apparatus. In this manner the register relays shown in Fig. 25 and certain of the lamp relays shown in Figs. 26 and 27 are operated in the same manner as they would be operated in a relay call indicator office. The lamp, to indicate a number or code, is lighted as each number or code is checked by the testing device. It is the practice in relay call indicator offices to light a plurality of lamps to indicate the complete number or code.

A check of the relay call indicator pulses sent out by the sender is made from various positions of the impulse sequence switch, Fig. 2. Its rotation associates the lamp relays with the register switches of the testing device and a lamp shown in Fig. 27 is lighted to indicate the setting of the lamp relays in each of the progressive positions of impulse switch, Fig. 2. It is necessary that the lamp relays be positioned in accordance with the setting of the register switch in the testing device to progressively rotate the impulse switch of Fig. 2 and the check switch of Fig. 5. The circuit to light each lamp shown in Fig. 27 is established through the register switches and lamp relay contacts. When the impulses sent out by the sender set the lamp relays incorrectly, a circuit is not established to rotate the impulse and check switches to check the next successive set of pulses and therefore the progressive movement of the testing device is arrested and an alarm is sounded. A lamp shown in Fig. 27 is lighted to indicate the number sent incorrectly by the sender.

When the registers of the sender are set for a tandem relay call indicator call, a check is first made of the tandem tens selection and one of the lamps of Fig. 27 is lighted to indicate the setting of the tandem tens relays. In this manner upon the setting of the tandem units relays, or the thousands relays, etc. one of the lamps of Fig. 27 is lighted. It will be recognized that this lamp indication is quite different from the relay call indicator lamp indicating device since only ten lamps are used in this circuit to indicate the success of any number of selections. These lamps, as controlled through the setting of the register switches, are sufficient to indicate the success of a test or a failure.

On the completion of all the tests of a sender the sender selector switch is advanced

and a second sender tested. When all the senders connected with one sender selector switch have been tested the master switches are advanced and those connected with another sender selector switch are tested. When all the non-coin senders have been tested the master switch is advanced to sender selector switches connected with coin senders. On master switch 1510 are leads, connected to terminals corresponding to 75 sender selectors connecting with the different types of senders, which control the operation of relays 1301, 1302 and 1303 to modify the action of the testing device to apply the correct tests for the different senders. 80

Keys are provided whereby any test may be made on any particular sender and for various other purposes.

Detailed description of the operation—non-coin senders. 85

Let it be assumed that the sequence switch and other apparatus of the testing device, Figs. 1 to 15, and 25 to 27 inclusive, are in their normal positions and that the testman desires to start a routine test of a group of senders, one of which is disclosed in Figs. 16, 18 to 24, inclusive and another in Figs. 17 to 24, inclusive. Also let it be assumed that a plurality of tests are to be made on each sender in the group of senders. To make a plurality of tests on each sender the multi-test key 1101 is operated. The actuation of start key 1401 starts a routine test of the group. 100

The actuation of start key 1401 establishes a circuit to operate start relay 1402 from grounded battery, right winding of relay 1402, right contact of sequence switch cam 1403, left outer contact of key 1401, right contacts of sequence switch cam 801, upper contacts of cam 501, lower contacts of cam 201, lower contact of cam 1304, left contact of cam 1201 to ground. The operation of relay 1402 establishes a circuit from grounded battery, winding of relay 1404, contact of relay 1402 to ground at the outer right operated contact of key 1401. Relay 1404 in attracting its left inner armature establishes a circuit to rotate sequence switch 1400 from position 1 to position 2. This circuit may be traced from battery, winding of sequence switch magnet 1400, lower left contact of cam 1405, inner left contact of relay 1404, outer left back contact of relay 1406 to ground. When sequence switch 1400 reaches position 13/4 a circuit is established for relay 1407 extending from battery, right winding of relay 1407, upper contacts of cam 1408, master selector brush 1511 and its normal contact to ground. Relay 1407 in attracting its left inner armature establishes a locking circuit for itself through its left winding and inner left armature, upper contact of cam 1409 to ground. The operation 115

110

120

125

130

of relay 1407 closes a circuit for advancing sequence switch 1400 to position 3 which may be traced from battery, through the winding of sequence switch magnet 1400, right contacts of cam 1426, outer left front contact of relay 1407, upper contact of contact of cam 1409 to ground. Switch 1400 is rotated to position 4 under the control of its master contact. When sequence switch 10 1400 leaves position 1 the circuit of relay 1402 is opened and that relay releases, opening the circuit for relay 1404 which also releases. Relay 1407 being operated, a circuit is established in position 4 of sequence switch 15 1400 for relay 1410 extending from grounded battery, resistance 1411, winding of relay 1410, right contact of cam 1412, outer left front contact of relay 1407 upper contact of cam 1409 to ground. The operation of relay 20 1410 closes a circuit from battery, winding of magnet 1400, lower left contact of cam 1413 to ground, at the contact of relay 1410. Sequence switch 1400 advances to position 5 in this circuit, opening the circuit of relay 1410 which releases. A circuit is established in position 5 to rotate sequence switch 1400 to position 6. This circuit may be traced from grounded battery, winding of magnet 1400, left contacts of cam 1426, outer 25 left front contact of relay 1407, upper contact of cam 1409 to ground.

The magnets of master switches 1500 and 1510 are now energized. The circuit established to energize the magnet of master switch 1500 may be traced from battery, through the winding of magnet 1501, upper left contact of cam 1416, to ground over the outer left front contact of relay 1407. The circuit established to energize the magnet of master switch 1510 may be traced through 30 battery, winding of magnet 1512, upper right contact of cam 1416 to ground over the outer left front contact of relay 1407. A circuit is also established for relay 1410 extending from battery, resistance 1411, winding of relay 1410, lower right contact of cam 1412, outer left front contact of relay 1407 to ground. At the same time a shunt circuit is prepared extending from battery, through 35 resistance 1411, upper right contact of cam 1417, back contact of magnet 1512, upper right contact of cam 1416 to ground over the outer left front contact of relay 1407, and a second shunt circuit over the upper left contact of cam 1417, back contact of magnet 1501 and the upper left contact of cam 1416 to ground over the outer left front contact of relay 1407. Relay 1410 is therefore prevented from operating until the magnets 40 1501 and 1512 operate, opening their back contacts. Upon the actuation of magnets 1501 and 1512 these shunts are removed and relay 1410 operates. The operation of relay 1410 establishes a circuit to rotate sequence switch 1400 from position 6 to position 7.

This circuit may be traced from battery through the winding of magnet 1400, lower left contact of cam 1413, to ground at the contact of relay 1410. The sequence switch upon rotating from position 6 to position 7 70 opens the circuits of the master switch magnets 1501 and 1512 and that of relay 1410, releasing them.

The release of the magnets causes the rotation of the brush sets from their normal 75 position to position 1, in the well known manner. The rotation of the master switches to position 1 associates the testing device with the first sender selector 1520. The terminals of this switch are associated 80 with the first twenty senders.

Sequence switch 1400 is now rotated to position 17. The energizing circuit may be traced from grounded battery, through the winding of magnet 1400, right contacts of cam 1426, outer left front contact of relay 1407, upper contact of cam 1409 to ground. In position 17 a test is made to ascertain 85 whether switch 1520 is in its normal position. The circuit established to make this 90 test rotates sequence switch 1400 from position 17 to position 18 and may be traced from grounded battery, through the winding of magnet 1400, lower left contact of cam 1431, normal contact and brush 1521 of 95 sender selector switch 1520, No. 1 contact and brush 1514 to master switch 1510, right back contact of relay 1404, winding of relay 1438, right contact of key 1102, upper right contact of cam 1449, to ground. If switch 100 1520 is not in its normal position the above traced circuit is not completed and switch 1400 is not advanced to position 18. Should switch 1400 remain in position 17 an unusually long time, the time alarm circuit shown 105 in Fig. 11 operates and functions as will be later described. In position 18 a circuit is established to energize sender selector switch magnet 1527 from grounded battery, through the winding of magnet 1527, brush 110 1513 and its associated contact, lower contact of cam 1416, to ground over the outer left front contact of relay 1407. An energizing circuit is also established for relay 1410 from battery through resistance 1411, winding of relay 1410, lower left contact of cam 1412, brush 1503 and its associated contact, brush 1511 and associated contact to ground. At the same time a circuit is closed in shunt 115 of relay 1410 extending from battery through resistance 1411, lower contact of cam 1417, brush 1502 and associated contact, back contact of magnet 1527, brush 1513 and associated contact, lower contact of cam 1416 to ground over the outer left front contact of relay 1407. This circuit prevents the 120 operation of relay 1410 until magnet 1527 operates. When the above traced shunt circuit is opened, relay 1410 operates and closes 125 a circuit for rotating sequence switch 1400 130

from position 18 to position 1 which circuit may be traced from battery, winding of switch 1400, lower left contact of cam 1413, to ground at the front contact of relay 1410. The rotation of the sequence switch from position 18 to position 1 opens the circuit of magnet 1527 to cause its release. Brushes 1521, to 1526 are now rotated from their normal position to position 1 to associate the testing device with the first sender to be tested. The holding circuit for relay 1407 and the energizing circuit of relay 1410 are also opened to cause their release.

In position 1 of sequence switch 1400 a circuit is again established to operate relay 1402 over the circuit previously traced. The operation of relay 1402 establishes a circuit for operating relay 1404 as above described. The operation of relay 1404 establishes a circuit to rotate the sequence switch from position 1 to position 2, to start a second revolution of the switch. The circuit for rotating sequence switch 1400 is the same as that previously traced. In position 2 the sender associated with the testing device through the terminals of switch 1520 is tested to ascertain whether it is a busy or idle condition. A busy sender is characterized by ground connected to a conductor (conductor 1831) as described in the patent to O. H. Kopp, No. 1,509,434, issued September 23, 1924. An idle sender is characterized by the absence of ground on this conductor. Upon the association of a testing device with a busy sender, a circuit is established to maintain relay 1402 in an actuated condition. This circuit may be traced from grounded battery, through the left winding of relay 1402, right front contact of relay 1404, brush 1514 and its associated contact, brush 1521 and its associated contact, conductor 1831 to ground either at the district selector associated with this sender or over the outer back contact of relay 1801 through the winding of relay 1802 to ground at the right front contact of that relay as will appear later.

In position 2 of sequence switch 1400, lamp 1104 is lighted to indicate that the sender is being tested to ascertain whether it is in a busy or idle condition. Should this lamp remain lighted a predetermined period of time, the time alarm circuit shown in Fig. 11 operates an audible signal to attract the attention of the test man, who is informed by the lighted condition of lamp 1104 that the test failed at this point. The detailed operation of the time alarm circuit will be hereinafter described.

Should a district circuit test a sender at the same time that a test circuit is making a busy test and the district relay and relay 1402 release simultaneously, thus connecting the district selector and test circuit to the same sender, relay 1438 is connected to con-

ductor 1831 over the right back contact of relay 1404 and brush 1514 and 1521 with their associated terminals one terminal of relay 1438 is connected to ground, at cam 1419 as previously described. Since the district selector immediately connects ground to conductors 1831 at the release of its relay, relay 1438 cannot operate. Ground is now connected over the outer left operated contact of key 1401, lower contact of cam 1439, left back contact of relay 1404, left back contact of relay 1421, contact of cam 1440, to interrupter 1441. When interrupter 1441 closes its lower contact, relay 1442 operates in a circuit from battery, through the winding of that relay, right contact of relay 1443, lower contact of interrupter 1441 to ground as traced. Relay 1442 locks over its inner left contact and the contact of cam 1440 to ground as traced, independent of the interrupter. When interrupter 1441 closes its upper contact, relay 1415 operates in the circuit from battery, through the winding of that relay, inner left normal contact of key 1418, outer right contact of relay 1442, upper contact of interrupter 1441, to ground as above traced. Relay 1103 also operates in a circuit from battery, through its winding, outer lower normal contact of repeat key 1115, inner right contact of relay 1442, upper contact of interrupter 1441 to ground as traced. Relay 1103 operates and locks to ground at cam 1449 and opens the circuit for advancing sender selector switch 1520. Relay 1415 operates and locks in a circuit through its right front contact, upper contact of cam 1409 to ground. The operation of relay 1415 also closes a circuit from battery through the winding of sequence switch magnet 1400, upper right contact of cam 1431, left front contact of relay 1415, inner left operated contact of start key 1401, left back contact of relay 1427, right back contact of relay 1406, outer left back contact of relay 1407, upper contact of cam 1409 to ground, advancing the sequence switch 1400 to position 17. As sequence switch 1400 passes through position 2½, relay 1443 is operated in a circuit from battery through the winding of the relay, outer left contact of relay 1442, upper left contact of cam 1439, outer right operated contact of key 1401 to ground. Relay 1443 locks when sequence switch 1400 reaches position 3 over its inner right contact and the right contact of cam 1439 to the same ground. The operation of relay 1443 opens the operating circuit of relay 1442. When sequence switch 1400 leaves position 15, relay 1442 releases and switch 1400 is advanced from position 17 to position 18 in a circuit from battery through the winding of the sequence switch magnet, lower right contact of cam 1405 back contact of relay 1414, left normal contact of key 1418, right back contact of relay 1438.

1407, lower right contact of cam 1428 to ground. In position 18 relay 1410 is again operated in a circuit from battery, through resistance 1411, winding of relay 1410, lower 5 left contact of cam 1412, brush 1503 and its associated contact, brush 1511 and its associated contact to ground. The circuit for operating the stepping magnet of switch 1520 is open at the back contact of relay 10 1103, hence the sender selector is not stepped to the next sender. The operation of relay 1410 closes a circuit from battery through the winding of sequence switch magnet 1400, lower left contact of cam 1413, front contact 15 of relay 1410 to ground advancing the sequence switch to position 1. When the sequence switch leaves position 18 the locking circuits for relays 1413 and 1103 are opened and these relays release. Relays 1402 and 20 1404 operate as previously described advancing sequence switch 1400 to position 2. If the sender is still in use by the district, the relay 1402 is held operated and lamp 1104 lights as previously described. 25 Assuming that an idle sender has been encountered, no circuit is established through the left winding of relay 1402 and, since the actuating circuit through its right winding is opened by the rotation of sequence switch 1400 from position 1 to position 2, this relay releases and in turn releases relay 1404. 30 The release of relay 1404 establishes a circuit to mark the sender busy to any district selector which may attempt to make a connection therewith and also serves to connect the sender with the testing device. This circuit may be traced from ground, through the upper right contact of cam 40 1449, right contact of key 1102, winding of relay 1438 right back contact of relay 1404, brush 1514 and its associated contact, brush 1521 and its associated contact, conductor 1831, outer back contact of relay 1801, back 45 contact of relay 1802, winding of relay 1803 to battery. Relay 1803 operates and closes a circuit from battery, winding of relay 1804, right front contact of relay 1803 to ground. Relay 1803 also closes a circuit 50 from battery, winding of relay 1902, right normal contact of relay 1809, right back contact of relay 1807, left back contact of relay 1903, back contact of relay 1900, left front contact of relay 1803 to ground. 55 Relay 1804 operates and closes a circuit from battery, through the winding of relay 1601, normal contact of relay 1601, brush 1611 of time alarm switch 1610 and its normal terminal, conductor 1828, right contact 60 of relay 1804 to ground. Relay 1601 operates and initiates the operation of the sender time alarm circuit. 65 The operation of the time measure and alarm switch 1610 is as follows: The operation of relay 1601 closes a locking circuit through its right contact, conductor 1828, to ground at the right contact of relay 1804. When interrupter 1604 closes its contact a circuit is completed from battery, winding of stepping magnet 1605, contact of interrupter 1604, normal terminal and brush 1606 of time measure switch 1610, left front contact of relay 1601, right contact of relay 1607, outer left contact of relay 1602 to ground. When the interrupter opens this circuit the switch is stepped to terminal 1 where the circuit is again closed on the closure of the interrupter contact stepping the switch to terminal 2 and thence to terminal 3. If the register control switch has not been advanced from normal, switch 1610 can not leave terminal 3 and a circuit is closed for sender monitor lamp 1608, which lights to indicate that dialing has not been started. 85 If the register control switch 2100 is stepped off normal as will be described hereinafter, a circuit is closed for relay 1607, from battery, through its winding, brush 1609 and its terminals normal to 5 inclusive, conductor 1814, terminals 1 to 8 and brush 2130 of switch 2100 to ground. The operation of relay 1607 closes a circuit from battery, through the winding and back contact of stepping magnet 1605, inner left contact 90 of relay 1607, brush 1609, and its normal to No. 5 terminals and thence to ground over No. 6 terminal in this circuit. Relay 1607 releases with switch 1610 on its No. 6 95 terminal. A circuit is now closed from battery, through the winding of magnet 1605, contact of interrupter 1604, terminals 6 to 8 and brush 1606, outer left contact of relay 1601, right contact of relay 1607, outer left 105 contact of relay 1602 to ground. The switch is stepped under the control of interrupter 1604 to terminal 9. 110 If switch 2100 has not yet reached terminal 9 a circuit is closed for flashing lamp 1608 through interrupter 1612, the No. 9 terminal and brush 1606 to ground as previously traced. The circuit for advancing switch 1610 from terminal 9 extends through the inner left contact of relay 1607, and 115 thence over the energizing circuit of relay 1607 which may be traced from battery, through the winding of relay 1607, brush 1609 and its No. 6 to No. 11 terminals, conductor 1820, terminal No. 9 and brush 2130 120 of switch 2100 to ground. Switch 1610 is stepped to its No. 12 terminal where the circuit of relay 1607 is maintained through the strapped terminals 12 to 16, right back contact of relay 1613, outer left contact of relay 1602 to ground to step the switch to its No. 17 terminal. Relay 1607 releases when switch 1610 leaves its No. 16 terminal. The circuit of stepping magnet 1605 is then completed through interrupter 1604, strapped 125 130

terminals 17 to 19, brush 1606, outer left contact of relay 1601, right contact of relay 1607, outer right contact of relay 1602 to ground. Switch 1610 is stepped under the control of interrupter 1604 to its No. 20 terminal. If the sender is not restored to normal at this time the circuit of lamp 1608 is completed through the left back contact of relay 1613, interrupter 1614, No. 20 terminal 10 and brush 1606, outer left contact of relay 1601, right contact of relay 1607, outer left contact of relay 1602 to ground.

If the sender has returned to normal, relay 1804 has been released and the circuit of relay 1601 is opened. The release of relay 1601 closes a circuit for relay 1607 through the winding of that relay, strapped off-normal terminals and brush 1615, left back contact of relay 1601 to ground. The operation 20 of relay 1607 closes a circuit for stepping magnet 1605 from battery, through the winding of magnet 1605 and its back contact, inner left contact of relay 1607, strapped terminals and brush 1615, inner 25 left contact of relay 1601, to ground, in which circuit switch 1610 is stepped back to normal, at which time the circuit of relay 1607 is opened and that relay releases.

It will be observed that the purpose of the time measure switch is to prevent the further extension of a call, and to display a signal at the sender monitor's position should the sender fail to operate at any point. It will, therefore, cause the operation of the time measure device of Fig. 11 to sound an alarm to attract the attention of the test man, who will be informed by means of lamps connected with the test circuits where the sender has functioned inaccurately. The sender monitor operator is informed that the sender is undergoing test by a tone connected to the tip and ring of jack 1616, in a manner to be described herein-after.

When relay 1804 is operated as above described, it also closes a circuit from battery, through the winding of relay 1805, inner left contact of relay 1804, inner back contact of relay 1801 to ground.

Since brush 1509 of master switch 1510 is engaging one of the non-coin sender selectors a circuit is completed in position 2 of sequence switch 1400 extending from ground at the upper contact of cam 1409, brush 1509 and its corresponding terminal, winding of relay 1302 to battery. The operation of relay 1302 controls the extension of calls to a particular zero operator but does not cause the operation of relay 1414 since it corresponds to non-coin senders.

Relay 1438 operates in the circuit previously traced for making the sender busy, and closes a circuit from battery through the winding of relay 1421 to ground at the contact of relay 1438. The operation of relay

1421 in turn closes a circuit through the winding of relay 1422 to ground at the left contact of relay 1421. Sequence switch 1400 is advanced from position 2 to position 3 in a circuit from battery through its winding, lower right and upper left contacts of cam 1426, left front contact of cam 1421, left back contact of relay 1404, lower contact of cam 1439, outer right operated contact of key 1401 to ground. Switch 1400 continues to rotate to position 4 under the control of its master cam.

At the same time that the circuit of relay 1807 is established, a circuit is closed from battery, through the right winding of relay 1900, conductor 1832, inner right back contact of relay 1602, sender selector brush 1524 and its associated contact, master selector brush 1515 and its associated contact, left contact of relay 1422, lower left contact of cam 804, winding of relay 803, upper left contact of cam 1423, inner left contact of relay 1422, brush 1504 and its associated contact, brush 1523 and its associated contact, outer right back contact of relay 1602, conductor 1833, left winding of repeating coil 1901 to ground. The operation of relay 803 performs no function at this time.

Relays 803 and 1900 operate in this circuit, the operation of relay 1900 closing a substitute circuit for relay 1902. Since relay 1902 is slow to release this circuit usually closes before relay 1902 releases, due to the opening of its circuit by relay 1807. The circuit of relay 1902 may be traced from battery, through the winding of that relay, front contact of relay 1900, left front contact of relay 1803 to ground. Relay 1900 also closes a circuit from battery (Fig. 16), conductor 1823, winding of relay 1809, inner front contact of relay 1807, left normal contact of relay 1809, front contact of relay 1900, left front contact of relay 1803, to ground. Relay 1809 operates and locks to ground at the left front contact of relay 1803. The operation of relay 1809 also closes a circuit for advancing sequence switch 1800 to position 2 which circuit may be traced from battery, winding of sequence switch 1800, lower left contact of cam 1840, inner left contact of relay 1809 to ground. Relay 1809 also closes a circuit from battery, winding of relay 1903, outer left contact of relay 1809, front contact of relay 1902 to ground. The operation of relay 1903 closes a circuit, through tone coil 1904, through the right winding of coil 1901, brush 2101 of switch 2100 and its normal contact, inner left contact of relay 1903 to ground. The tone produced in this circuit is that used to inform the subscriber that he may proceed to dial.

With switch 1400 in position 4 and relays 1421 and 1422 operated, a circuit is closed for advancing the route control sequence

switch 1300 to position 2 to set the registers of the test set to test the ability of the sender to control the establishment of a full mechanical interoffice call including P. B. X. 5 dialing. This circuit may be traced from battery, through the winding of magnet 1300, upper contact of cam 1331, upper operated contact of key 1101, lower contacts of cam 528, left contacts of cam 822, left 10 contacts of cam 1426, left front contact of relay 1421, left back contact of relay 1404, left back contact of relay 1415, inner left closed contact of key 1401, left contact of relay 1427, right back contact of relay 1406, 15 left back contact of relay 1407 to ground at the upper contacts of cam 1409. As soon as sequence switch 1300 reaches position 2 relay 322 is operated in a circuit through its winding, conductor 601, upper contact of cam 20 1324, inner left back contact of relay 1317, and thence over the circuit traced for advancing sequence switch 1300 to position 2 to ground. The operation of relay 322 connects battery to the district, office and code 25 register relays.

The setting of route control switch 1300 determines the setting of the registers in the sender by positioning the registers of the testing device. District brush register 350, 30 district group register 600, office brush register 615, office group register 630, code A register 645 and code B register 660 are set in accordance with cross connection wiring between terminals associated with the cams of 35 each register switch and the terminals on cross connecting racks 1375 and 1376 associated with route control switch 1300. All of the magnets controlling the rotation of the register switches are energized at one 40 time. The circuit for operating these magnets may be traced as follows. The circuit established to operate district brush register magnet 350 may be traced from battery, winding of magnet 350, lower contact of cam 351, a terminal on rack 352 cross connected to a terminal on rack 1375, upper right contact of cam 1306 to ground. It will be noted 45 that this circuit is established in positions 2+6, 8+12 and 14+18 of this sequence switch and therefore the district brush register will be arrested in its rotary movement in position 1, 7 or 13. The district group register 600 is arrested in its rotary movement in position 9 or 18, since the operating 50 circuit for magnet 600 is through the lower left contact of cam 626, a terminal on rack 608 cross connected to a terminal on rack 1376, upper right contact of cam 1307 to ground. The office brush register 615 is arrested in position 3 since the actuating circuit for magnet 615 is through the lower 55 contact of cam 627, a terminal on rack 610 cross connected to a terminal on rack 1376, lower right contact of cam 1308 to ground.

60 This particular cross connection for office

brush register switch 615 is the skip office wiring and therefore office group register switch 630 is not set for this test. The code register switches 645 and 650 are set under the control of the route control switch to positions which correspond to the positions set up on the district brush, district group, office brush and office group switches. Switch 645 is stopped in position 3 since magnet 645 is energized in a circuit over the lower left contact of cam 628, a terminal on rack 613 cross connected to terminal rack 1375, upper right contact of cam 1310 to ground. The code B register switch 660 is arrested in position 5 since the actuating circuit for magnet 660 is 70 through the upper right contact of cam 629, a terminal on rack 635, cross connected to terminal rack 1375, lower right contact of cam 1325 to ground. As each switch is set 75 the associated relay is operated from battery, at the front contact of relay 322, through relays 358, 602, 603, 605, and 606 in parallel through cams corresponding to those employed in setting the register switches to ground over the same cross connecting terminals, as soon as the register switches come 80 to their positions of rest. When relays 358, 602, 603, 605 and 606 have all energized a circuit is closed for advancing switch 1200 to 85 position 2 and operating relay 1213. This circuit may be traced from battery, through the winding of magnet 1200, lower contact of cam 1214, and from battery through the winding of relay 1213, back contact of relay 1215 and thence over the contact of relay 606, 90 contact of relay 605, contacts of cam 632, contact of relay 603, contact of relay 602, contact of relay 358 to ground.

95 It is to be noted that when office brush register takes a position corresponding to a skip office wiring and the office group register is not set, a path is provided over cam 632 for completing the above traced circuit. In other positions of the office brush register, office group register is set and the circuit above 100 traced is completed over the contact of relay 604.

105 Switch 1200 in position 2 establishes a circuit to position numerical and station registers 675, 900, 915, 930, 945, 960 and 975. The 110 circuit for thousands register 675 may be traced from battery, through the winding of magnet 675, upper contact of cam 616, lower contact of cam 1204, to ground. The circuit for the hundred register may be traced from 115 battery, through the winding of magnet 900, left contact of cam 901, upper contact of cam 1205 to ground. The circuit for the tens register magnet may be traced from battery, 120 through the winding of magnet 915, upper right contact of cam 902, lower right contact of cam 1207, to ground. The circuit for the units register magnet may be traced from battery, through magnet 930, upper left contact of cam 903, lower left contact of cam 125

- 1208, to ground. The circuit for stations hundreds register magnet may be traced from battery, through the winding of magnet 945, upper right contact of cam 904, upper right contact of cam 1209, to ground. The circuit for stations tens register magnet may be traced from battery, through the winding of magnet 960, contact of cam 905, lower left contact of cam 1209, to ground. 10. The circuit for stations units register magnet may be traced from battery, through the winding of magnet 975, contact of cam 906, lower left contact of cam 1210, to ground.
- An inspection of the drawings will show 15. that the thousands register comes to rest in position 5, the hundreds register in position 4, the tens register in position 1, the units register in position 5, the stations hundreds register in position 7, the stations tens register in position 10, and the stations units register in position 10.

At the same time circuits are closed for setting the class and talking selection register switches 320 and 300. These switches are 25. set in a manner similar to the code, district and office registers. The circuit for rotating magnet 320 may be traced from battery, winding of magnet 320, lower right contact of cam 323, upper right contact of cam 1210, to ground. The circuit for magnet 300 extends from battery, through the winding of magnet 300, upper contact of cam 324, a terminal on rack 306 cross connected to a terminal on rack 1216, upper right contact 35. of cam 1202 to ground. When switches 300 and 320 come to rest, circuits are closed for relays 301 and 302 from battery, front contact of relay 1213, conductor 617, thence in parallel through the winding of relay 301, lower left contact of cam 303, to ground, at the upper right contact of cam 1210, and through the winding of relay 302, upper contact of cam 305 by way of the same terminals of cross connecting racks 306 and 45. 1216 used in moving switch 300 to ground.

With the numerical registers and the class and talking selection registers set, a circuit is completed for operating relay 832, as soon as interrupter 833 closes its upper contact, which may be traced from battery, through the left winding of relay 832, upper contact of interrupter 833, contact of relay 803, upper contact of cam 529, upper contact of cam 907, upper contacts of cam 908, upper contacts of cam 909, upper contacts of cam 910, upper contacts of cam 911, upper contacts of cam 912, upper contacts of cam 618, contact of cam 1212, contact of relay 301, contact of relay 302, outer upper operated contact of key 1101, lower contacts of cam 528, left contacts of cam 822, left contacts of cam 1426, left front contact of cam 1421, left back contact of relay 1404, left back contact of relay 1415, inner left operated contact of relay 1401 back contact of relay

1427, right back contact of relay 1406, left back contact of relay 1407, upper contact of cam 1409 to ground. Relay 832 operates and locks over its inner right contact to ground over the circuit just traced independent of the interrupter. When interrupter 833 closes its lower contact, a circuit is completed from ground as just traced over the lower contact of the interrupter, outer right contact of relay 832, lower right contact of cam 807, winding of sequence switch magnet 809 to battery advancing the sequence switch to position 2.

When sequence switch 800 moves from position 1 to position 2 the circuit previously traced for relay 803 is opened at cam 804, simulating a preliminary or false pulse such as sometimes occurs from accidental jarring of the switchhook preceding the operation of the dial by the subscriber. The advance 85 of sequence switch 800 to position 2 also releases relays 301, 302 and 322 in turn releasing relays 358, 602, 603, 605 and 606. The release of relay 803 opens the circuit of relay 832 and that relay releases.

The opening of the circuit of relay 803 also causes the release of relay 1900 and that relay closes at its back contact a circuit extending from battery, through the left winding of relay 1905 and resistance 1906 in parallel, through the winding of magnet 2102 of A register switch 2103, right back contact of relay 1907, brush 2104 of register control switch 2100 and its normal contact, winding of slow-release relay 1908, outer left front contact of relay 1903, back contact of relay 1900, left front contact of relay 1803, to ground. Magnet 2102 and relay 1908 are energized in this circuit. At the same time a circuit is closed from battery, at the left back contact of relay 1907, through the winding of relay 1910, upper contacts of cam 1837, brush 2106 and its normal contact A, back contact of magnet 2102, right back contact of relay 1907, brush 2104 and 105 its normal contact, winding of relay 1908, outer left front contact of relay 1903, back contact of relay 1900, left front contact of relay 1803 to ground. Relay 1910 energizes in this circuit, connecting ground to the circuits of relays 1902 and 1908 and magnet 2102 until magnet 2102 opens its contact to insure the operation of magnet 2102 in case the interruption of the dialing circuit is very brief.

The energization of relay 1908 closes a circuit from battery, through the right winding of relay 1905 and resistance 1909 in parallel, winding of magnet 2105 of register control switch 2100, right front contact of relay 1908, inner right contact of relay 1903 to ground. Magnets 2105 and 2102 attract their armatures but do not step their respective switches as long as their circuits are maintained closed.

- With sequence switch 800 in position 2 a circuit is closed for moving impulse sequence switch 200 out of position 1 which circuit may be traced from battery, through the 5 magnet winding, upper right contact of cam 202, upper right contact of cam 816 to ground. With the switch 800 in position 2 the tip and ring leads from the sender are again closed. The circuit may be traced 10 from battery, through the right winding of relay 1900, conductor 1832, inner right back contact of relay 1602, brush 1524 and its associated contact, brush 1515 and its associated contact, contact of relay 1422, upper 15 left contact of cam 804, conductor 1001, lower contact of cam 1312, upper inner normal contact of key 1313, conductor 1002, left back contact of relay 809 to cam 701, lower contact of that cam, lower left contact of 20 cam 810, conductor 1003, lower contacts of cam 1314, upper outer normal contact of key 1313, conductor 1004, upper left contact of cam 1423, inner left contact of relay 1422, brush 1504 and its associated contact, brush 25 1523 and its associated contact, outer right back contact of relay 1602, conductor 1833, left winding of repeating coil 1901 to ground. Across this circuit is bridged a low resistance subscriber's substation ringer 30 circuit 1315, being connected to conductor 1003 in the previously traced circuit by way of cam 1314 through the lower inner normal contact of key 1316 and lower inner normal contact of key 1313 and to conductor 1002 35 directly. High resistance 811 is also bridged across the circuit to simulate a leak.
- Relay 1900 reoperates in the above traced circuit. The operation of relay 1900 opens the circuit previously traced for relay 1908 40 and magnet 2102. Magnet 2102 retracts its armature and steps its brushes to its first off normal contact. Relay 1900 remains energized long enough to permit the deenergization of relay 1908. Magnet 2105 is prevented 45 from releasing in a circuit extending from battery, through the right winding of relay 1905 and resistance 1909 in parallel, winding of magnet 2105, brush 2109 of the A code register and its first off-normal contact, outer right back contact of relay 1911, inner left contact of relay 1903 to ground. With relay 1908 deenergized and switch 2103 on its first off normal contacts, a circuit 50 is closed from battery, left back contact of relay 1908, left winding of relay 1907, brush 2108 and its first off-normal contact, right back contact of relay 1908 to ground at the inner right contact of relay 1903.
- When switch 800 reaches position 1 1/2, in moving to position 2 as previously described, relay 812 operates in an obvious circuit and locks through its inner left contact and middle right back contact of relay 809, lower

left contact of cam 702, upper right contact of cam 1428, to ground.

As soon as sequence switch 800 reaches position 2 and interrupter 834 closes its contact a circuit is completed for relay 835 from battery through the winding of the relay, contact of interrupter 834, upper right contact of cam 816 to ground. Relay 835 operates and locks over its right front contact to the same ground independent of the interrupter. With relays 812 and 835 operated a circuit is closed for driving interrupter 750 through one revolution. This circuit may be traced from battery through the winding of magnet 750, contact of cam 703, inner right back contact of relay 809, 80 inner right contact of relay 812, outer right contact of relay 835, lower left contact of cam 845, and lower right contact of cam 324 to ground.

Sequence switches 700 and 750 are used as pulsing interrupters and are driven by special means to accurately control the number of revolutions per minute. Switch 700 is a low speed interrupter used to simulate slow dial pulses with each pulse of equal time duration. Switch 750 is a high speed interrupter to simulate fast dial pulses, each pulse of equal time duration. Since relay 809 is in its normal position, the high speed interrupter is used for this test.

As high speed interrupter 750 rotates, the above traced dialing circuit is maintained closed until the sequence switch arrives in position 3. As the interrupter moves through positions 3, 4, 5, 6, etc. the contact of cam 701 is opened momentarily to simulate dial pulses.

When switch 750 passes through position 3 relay 1900 is deenergized and closes its back contact. It will be remembered that switch 2103 has already been stepped to its first off-normal position and that relay 1907 is operated. A circuit is now closed from battery, through the left winding of relay 1912 and resistance 1913 in parallel, through the right winding of relay 1907 and its right contact, brush 2104 and its normal contact, winding of relay 1908, outer left front contact of relay 1903, back contact of relay 1900 to ground at the left front contact of relay 1803. Relay 1908 operates and opens the circuit through the left winding of relay 1907. Relay 1907 remains operated however, until relay 1900 again attracts its armature at the end of the first interruption of its circuit. Relay 1908 being slow to release, holds its armatures attracted throughout the series of pulses. When the circuit of relay 1900 is again closed, relay 1907 releases and closes the circuit for magnet 2102 so that the second interruption causes the advance of switch 2103 to its second position and the remaining impulses serve to advance the

switch to the desired position. Each time that the contact of cam 701 is opened relay 1900 releases and closes the previously traced operating circuit for magnet 2103 to 5 step switch 2103 as previously stated. Magnet 2105 is held energized as long as relay 1908 remains operated. At the completion of the series of pulses, relay 1908 releases permitting magnet 2105 to retract its armature and step control switch 2100 to its first off-normal position. The number of pulses to be sent by switch 750 is determined by the closure of a circuit in parallel with cam 701 which shunts all pulses except those desired to be sent. In the case of the code A pulses which are those first sent, this circuit may be traced from cam 701, through the upper contact of cam 704, lower right contact of code A register cam 619, upper right 10 contact of cam 815 to the contact of cam 701.

It will, therefore, be seen that only two pulses will be sent for the A code register 2103, one in position 3 and one in position 25 4 of switch 750. This shunt circuit is maintained until switch 750 arrives in position 1 when switch 750 comes to rest. When switch 750 leaves position 2, relay 812 releases. When switch 750 leaves position 12, relay 30 835 releases. When switch 750 leaves position 13 a circuit is closed for moving control switch 800 from position to position, in this case from position 2 to 3, which circuit may be traced from battery, through the winding of magnet 800, lower left contact of cam 807, left back contact of relay 812, outer right back contact of relay 809, lower right contact of cam 702, upper right contact of cam 1428, to ground. As switch 800 passes 35 through position 2½ relay 812 is energized and locks as before over the lower left contact of cam 702, of switch 750. The relay 835 is also operated as before and locks. As soon as switch 750 reaches position 1, it is 40 started on another revolution by means of the circuit previously traced through the left contact of relay 835, right contact of relay 812, innermost right back contact of relay 809, and lower contact of cam 703. This second series of pulses corresponds to 45 the code B series as dialed. Relay 1900 releases at each opening of this circuit and closes the circuit for advancing switch 2110 which circuit may be traced from battery through the left winding of relay 1905, 50 winding of magnet 2111, brush 2104 and its first off-normal contact, winding of relay 1908, outer left front contact of relay 1903, back contact of relay 1900 to ground at the 55 left front contact of relay 1803.

Magnet 2111 steps the B register one step for each release of relay 1900 as described for register 2103 positioning its brushes in accordance with the number of pulses trans-

mitted. Relay 1908 is maintained energized through the series of pulses and holds magnet 2105 operated as previously described. Since the code B register 660 was set in position 5 the shunt around the interrupter contact 701 is not closed until 65 switch 750 reaches position 6¾, that is, until four pulses have been sent out. This shunt circuit may be traced from cam 701, lower contact of cam 706, upper left contact of cam 636, lower contact of cam 815, to the contact of cam 701. After the four pulses have been sent out and register 2110 is in its fourth position, relay 1908 releases permitting magnet 2105 to retract its armature and advance register control switch 2100 to 70 its second off-normal position in which position the pulsing circuit is closed to the thousands register 2112. The thousands register 2112, hundreds register 2113, tens register 2300, units register 2301, stations hundreds 75 register 2302, station tens register 2303 and station units register 2304 are each set in a manner similar to the setting of the A and B registers 2103 and 2110. The register control switch 2100 is advanced one position 80 after the setting of each switch as previously described.

The power driven translator is shown in schematic form as indicated by switch assemblies 2114 and 2115. The control of the translator takes place as soon as register control switch 2100 is stepped to position 2. When the register control switch is thus positioned a circuit is closed to operate relay 1914 from grounded battery through the winding of relay 1914 and its normal contact, brush 2102, and its second, third and fourth off normal contacts, inner left front contact of relay 1903 to ground. Relay 1914 in operating establishes a locking circuit for itself through its right armature, lower contacts of cam 1838 to ground at the inner left front contact of relay 1903. The operation of relay 1914 further establishes circuits to 95 energize magnets 1915 and 1916, which magnets control the translators 2114 and 2115 in their rotary movement. The operation of relay 1914 also connects ground to the arc served by translator hunting brushes 2116 and 2117 over a path extending from ground at the inner left contact of relay 1903, outer back contact of relay 1911, innermost left contact of relay 1914, brush 2118 of A register 2103 and its second off normal contact, brush 2119 of B register 2110 and its seventh off normal contact, to contacts of the arcs served by brushes 2116 and 2117. As soon as brushes 2116 and 2117 encounter these 100 grounded terminals, a circuit is closed over brush 2216, through the windings of stop magnet 1917 and relay 1918 in parallel to battery; and through brush 2117 through the windings of stop magnet 1919 and relay 105 110 115 120 125

1920 in parallel to battery. Magnets 1917 and 1919 and relays 1918 and 1920 operate in this circuit. The operation of magnet 1919 opens the circuit of rotary magnet 1915 and brings translator 2115 to rest. The operation of magnet 1917 opens the circuit for rotary magnet 1916 and brings translator 2114 to rest. Since corresponding terminals are grounded on the two translator switches, 10 these switches will come to rest in corresponding positions. The setting of the translator is controlled by the joint setting of the code registers 2103 and 2110 to control the positioning of district and office 15 selectors in their brush and group selections. The operation of relay 1918 closes a substitute locking circuit for relay 1914 which extends from battery, through the winding of relay 1914 and its right contact, lower left contact of cam 1838, inner left contact of relay 1918 to ground.

Relays 1918 and 1920 also close locking circuits for themselves to the left front contacts of relay 1914. The joint operation of 20 relays 1918 and 1920 closes circuits for advancing sequence switch 1800 into position 3 and sequence switch 2000 into position 2. The circuit for magnet 1800 may be traced from battery, through the winding of that 25 magnet, upper right contact of cam 1840, outer right contact of relay 1920, outer right contact of relay 1918 to ground. The circuit for magnet 2000 may be traced from battery through the magnet winding, lower right contact of cam 2001, inner right contact of relay 1920, inner right contact of relay 1918 to ground.

The operation of relay 1920 also closes a 30 circuit for positioning the class sequence switch 2200 which circuit may be traced from battery, through the windings of magnet 2200 and relay 2201 in parallel, upper left contact of cam 2202, a terminal of rack 2203, conductor 2204, translator brush 2120 35 and its corresponding terminal, left back contact of relay 2205, inner left contact of relay 1920 to ground. Magnet 2200 and relay 2201 are energized in this circuit and magnet 2200 rotates the sequence switch to 40 position 8 which is the position corresponding to the call of the class for which the sender is being tested.

In the meantime relay 812 is released and 45 advances sequence switch 800 to position 3. For this class of call there is no 10,000 digit. Switch 800 is advanced from position 4 to position 5 immediately after the sending of the B code pulses in a circuit which may be traced from battery, through the winding 50 of magnet 800, upper left contact of cam 823 and thence to ground at the lower right contact of cam 324. The numerical and stations registers are now set in response to successive revolutions of switch 750. Each revolution of switch 750 causes switch 800 to

advance one position so that at the completion of the stations units setting, switch 800 will be in position 12.

In positions 11 and 12 of sequence switch 800 a circuit is established from battery, 70 through the winding of relay 1317, inner upper operated contact of multi-test key 1101, upper contacts of cam 818 to ground at the upper left contact of cam 203. Relay 1317 operates and locks over its inner right contact, lower contact of cam 1309 to ground. The operation of relay 1317 closes a circuit through the winding of relay 1215, outer right front contact of relay 1317 to ground. The operation of relay 1215 opens the circuit of relay 1213 in turn releasing relays 301 and 302. The operation of relay 1215 75 closes a circuit from battery, through the winding of magnet 800, upper left contact of cam 807, right front contact of relay 1215 to ground. Sequence switch 800 advances to 80 position 13, and then from position 13 to position 14 under the control of its master cam. Since this first sender under test is one used with non-coin lines, sequence switch 800 is immediately advanced to position 17 85 in a circuit extending from battery, through the winding of magnet 800, lower left contact of cam 817, outer left back contact of relay 819 to ground. 90

When switch 800 passes position 113 $\frac{1}{4}$ a circuit is completed from battery, right winding of relay 1900, conductor 1832, inner right back contact of relay 1602, brush 1524 and its associated contact, brush 1515 and its associated contact, outer left contact of relay 1422, upper left contact of cam 804, conductor 1001, lower contact of cam 312, inner upper normal contacts of key 1313, conductor 1002, upper contact of cam 327, right winding of repeating coil 820, contact of cam 802, conductor 1003, lower contacts of cam 1314, outer upper normal contact of key 1313, conductor 1004, inner left contact of relay 1422, brush 1504 and its associated contact, brush 1523 and its associated contact, outer right back contact of relay 1602, conductor 1833, left winding of coil 1901 to ground. This circuit holds the sender relay 1900 operated. 115

A source of tone current 821 is connected to the secondary of repeating coil 820 and a tone current is induced in the above traced circuit to notify the sender monitor operator that the circuit is under test, in case the test circuit or sender circuit should fail and display a signal before that operator. 120

With the sender control sequence switch 1800 in position 3 and the sender sequence switch 2000 in position 2 the sender is in condition to control district brush selection in the manner well known in the art and set forth in the above mentioned patent to O. H. Kopp, No. 1,509,434 issued September 23, 1924. This is accomplished in serv- 125 130

ice connections by the establishment of a fundamental circuit including a relay of the associated district selector and the stepping relay of the sender. The stepping relay of the sender is repeatedly deenergized by a shunt circuit through the commutator of the selector switch and controls a circuit including a particular counting relay which is determined by the setting of the translator.

To test the operation of the sender in this function, a fundamental circuit is established including a relay of the test circuit and the stepping relay of the sender.

15 This fundamental circuit may be traced from battery, through the winding of relay 100, left contact of the No. 10' counting relay, left contact of key 101, left contact of relay 102, left contact of relay 115, lower contact of cam 204, upper right contact of cam 507, right contacts of cam 822, inner right contact of relay 1422, master selector brush 1505 and its associated contact, brush 1525 and its associated contact, conductor 1818, back contact of relay 2002, outer left back contact of relay 1806, upper right contact of cam 1841, lower left contact of cam 2003, right winding of relay 2207, back contact of relay 2208, winding of stepping relay 2209, resistance 2005, upper contact of cam 1839, upper contact of cam 2006 to ground. Relays 100 and 2209 operate in this circuit but the direction of current is such that relay 2207 is not operated. The 30 operation of relay 2209 closes a circuit from battery, contact of cam 1842, winding of the No. 0 counting relay, conductor 2021, brush 2121 of translator 2115 and its corresponding contact, lower left contact of cam 2008, upper left contact of cam 2009, upper right contact of cam 1843, outer right contact of relay 2210, right contact of cam 2010, front contact of stepping relay 2209, lower left contact of cam 2006 to ground. 35 The No. 0 counting relay operates in this circuit and closes a locking circuit for itself through the winding of the No. 0' counting relay, and relay 2208 in parallel contact of the No. 0 counting relay, lower left contact of cam 2011 to ground. The No. 0' counting relay and relay 2208 do not operate in this circuit since they are shunted by ground over conductor 2007.

With switch 500 in position 1 a circuit is closed from battery, upper left contact of cam 508, through lamp 509, right contact of cam 214 left contact of cam 308 through lamp 919 to ground; lamp 509 indicating that district brush selection is being tested and lamp 919 that the district brush register is set in position 1.

Relay 100 closes a circuit for itself independent of the contact of relay 102 extending through its winding, back contact of the No. 10' counting relay, left contact of key

101, outermost front contact of relay 100 and thence as previously traced over the back contact of relay 1115 to the stepping relay of the sender. The operation of relay 100 also closes a circuit from battery, through the left winding of relay 102, left contact of cam 205, innermost contact of relay 100 to ground. A circuit is also closed for relay 510 from battery, winding of relay 510, left contact of cam 205, innermost contact of relay 100 to ground. Relay 510 opens the circuit of relay 511 to prevent the advance of switch 500 until the test of district brush selection is completed.

The operation of relay 100 also connects the upper contact of interrupter 104 to the back contact of relay 105. When the interrupter closes this contact relay 106 operates through a circuit extending from ground over the contact of interrupter 104, middle contact of relay 100, back contact of relay 105, winding of relay 106, conductor 109, upper contact of cam 206, upper contact of cam 512 to battery. Relay 106 operates and short circuits the windings of relays 105 and 107 from ground over the lower contact of cam 513, lower contact of cam 207, front contact of relay 106 to the windings of relays 105 and 107 opposite that to which ground is connected through interrupter 104 and the back contact of relay 105. When interrupter 104 opens its contact, ground is removed from one terminal of relays 105 and 107 and these relays operate in parallel with each other and in series with relay 106. This circuit may be traced from ground, lower contact of cam 513, lower contact of cam 207, contact of relay 106, windings of relays 105 and 107 in parallel, winding of relay 106, upper contact of cam 206, upper contact of cam 512 to battery. Relay 105 in operating prepares a circuit from interrupter 104, middle contact of relay 100, front contact of relay 105, back contact of the No. 0' counting relay, winding of the No. 0 counting relay, upper contact of cam 206, upper contact of cam 512 to battery. Relay 107 in operating prepares a circuit from interrupter 104, over the front contact of relay 107, outer contact of relay 100, to the fundamental circuit as previously traced. The interrupter contacts are so arranged as to close these two circuits simultaneously. The operation of interrupter 104 simulates the selector switch commutator by grounding the fundamental circuit at the point between relay 100, which simulates the selector relay, and the sender stepping relay.

When interrupter 104 next closes its contacts it completes the above prepared circuit of the No. 0 counting relay. When the No. 0 counting relay operates it closes a locking circuit for itself through the winding of the No. 0' counting relay, contact of the No. 0 counting relay, lower contact of cam

- 207, lower contact of cam 513 to ground. The No. 0' counting relay does not operate in this circuit as long as the interrupter contact remains closed, since it is shunted.
- 5 By the closure of its lower contact interrupter 104 connects ground through the front contact of relay 107, outermost contact of relay 100, left contact of key 101, back contact of the No. 10' counting relay, 10 winding of relay 100 to battery, holding relay 100 operated and shunting the stepping relay 2209 of the sender.
- It will be remembered that the operation of the stepping relay 2209 closed a circuit for the No. 0 counting relay of the sender. When relay 2209 releases, it removes the shunt around the No. 0' counting relay and relay 2208 and permits these relays to energize. The energization of relay 2208 opens 20 the fundamental circuit releasing relay 100 and preventing the re-operation of relay 2209. The operation of the No. 0' counting relay of the sender closes a circuit from battery, through the winding of sequence 25 switch magnet 2000, upper left contact of cam 2001, lower right contact of cam 1844, inner left back contact of relay 2210, contact of No. 0' counting relay to ground. The sender sequence switch is advanced to 30 position 4 in readiness to control district group selection. In passing from position 2 to position 4, the sequence switch opens the circuits of the counting relays including relay 2208 and these relays release.
- 35 The release of relay 100 disconnects interrupter 104 from the fundamental circuit and from the counting relays of the test set. This permits the No. 0' counting relay of the test circuit to operate in the locking circuit of the No. 0 counting relay previously traced. The deenergization of relay 100 also releases relay 510 permitting the energization of relay 511 from battery, winding of that relay, back contact of relay 510, upper right contact of cam 514, left contact of cam 328, back contact of the No. 1 counting relay of the test circuit, front contact of the No. 0 counting relay, to ground over conductor 108. The operation of relay 511 45 closes an obvious circuit for advancing sequence switch 500. When sequence switch 500 leaves position 1 the circuit of relay 511 is opened and the sequence switch comes to rest in position 2.
- 50 In passing from position 1 to position 2 sequence switch 500 also opens the circuits of the counting relays of the test circuit and of progress lamp 509 and match lamp 919.
- 55 If the particular counting relays operated in Fig. 1 do not agree with the setting of the register in the testing device, which may be due to incorrect setting of the sender register or inaccurate control of selection by 60 the sender, the circuit for relay 511 is not established and the sequence switch 500 can not move from position 1. If the sequence switch 500 remains in position 1, or any other position, for an undue length of time, the time alarm circuit in the lower portion 70 of Fig. 11 is actuated to sound an alarm. The test man upon investigating notes the position of the testing device as shown by lamp 509 and the setting of the register as shown by lamp 919. He operates key 110 75 which establishes circuits for relays 111 and 112 which provide battery for lighting one of the lamps of Fig. 1. A circuit is, therefore, established from battery, through one of the lamps, over the back contact of the 80 first non-operated counting relay and the front contacts of the operated counting relays to ground over conductor 108. For example, suppose that the Nos. 1 and 1' counting relays were operated in addition to the 85 Nos. 0 and 0' relays of the testing circuit. A circuit would be established from battery, through the next to the innermost contact of relay 112, through lamp 116, back contact of Nos. 1 and 0 counting relays to ground over conductor 108. The lighting of lamp 116 indicates that one more set of counting relays have been operated than should have been as indicated by the lighting of the No. 95 0 lamp of Fig. 9.
- It will be well at this time to describe the operation of the time alarm circuit of Fig. 11. When start key 1401 was operated, a circuit was closed from battery, through 100 the winding of relay 1107, brush 1106 and its normal contact, outer right closed contact of key 1401 to ground. Relay 1107 operates and locks over its left contact, contact of key 1127 and the contacts of cam 813 to 105 the same ground. Ground is also furnished from cam 1454 of sequence switch 1400 to maintain the circuit until that sequence switch reaches normal, should the start key be opened. The operation of relay 1107 110 closes a circuit from interrupter 1108 through the outer right contact of relay 1107, strapped contacts and brush 1109, winding of stepping magnet 1110 to battery. Time alarm switch 1100 is stepped in this 115 circuit from position to position.
- If the test has not been completed by the time that switch 100 reaches its 14th contact, a circuit is completed at that time from battery, through lamp 1111, through the No. 120 14 contact and brush 1112 inner front contact of relay 1107, to ground, lighting lamp 1111. A circuit is also completed through the winding of relay 1113 at the alarm board and an audible signal 1126 is operated. 125 Sufficient time is allowed to permit the completion of the longest test. At the completion of each test sequence switch 800 passes through position 1 and the contacts of cam 813 are opened. The opening of the con- 130

tacts of cam 813 permits the release of relay 1107 which closes a circuit from battery, through the winding of stepping magnet 1110, back contact of magnet 1110, brush 1114, and its strapped contacts to ground at the inner back contact of relay 1107. Switch 1100 is stepped in this self-interrupting circuit back to normal after which the above described cycle of operations is 10 repeated for each test.

Assuming that the circuit functioned correctly and relay 511 operated, switch 500 is advanced to position 2. When switch 500 leaves position 1 1/4, the circuit previously traced through relay 1807 to cam 506 is extended through resistance 523, alone, the circuit for resistance 522 being opened when sequence switch 500 leaves position 1 1/2. There is sufficient overlap to prevent the 15 opening of the circuit in passing from position 1 1/2 to position 1 3/4. When sequence switch 500 leaves position 2 this circuit is extended through the windings of relays 502 and 503 in parallel with resistance 523 and 20 with each other. Relay 503 operates in this circuit but relay 502 being marginal does not. The operation of relay 503 closes an obvious circuit for relay 530 which operates. A circuit is thereupon closed from battery, 25 through winding of magnet 200, upper right contact of cam 208, upper contacts of cam 516, front contact of relay 530, back contact of relay 502, right contact of cam 310, back contact of relay 511 to ground. 30 Switch 200 advances in this circuit to position 3.

With sequence switch 500 in position 2, district group lamp 517 is lighted in a circuit from battery, through the upper right 40 contact of cam 508, lamp 517, upper left contact of district group register cam 633 through the No. 8 lamp 920 to ground indicating that the sender is being tested for its ability to control district group selection and that the No. 8 district group is to 45 be selected.

The fundamental circuit previously described is reestablished in position 3 of sequence switch 200 and position 2 of sequence 50 switch 500. Relays 100 and 2209 reoperate in this circuit. Relays 102 and 510 are again operated and the cycle of operations for relays 105, 106, and 107 is repeated preparing the circuits for connecting interrupter 104 55 to the counting relays of the testing circuit and the fundamental circuit. The operation of relay 2209, at this time, closes a circuit from battery, contact of cam 1842, through the winding of the No. 8 counting 60 relay of the sender, back contact of the No. 8' counting relay, conductor 2013, to the district group arc of translator 2115, brush 2122, lower right contact of cam 2008, upper left contact of cam 2009, upper right contact 65 of cam 1843, outer right back contact of re-

lay 2210, left contact of cam 2010, front contact of the stepping relay 2209, right contact of cam 2006 to ground. When interrupter 104 rotates, the stepping relay of the sender is shunted to operate the counting 70 relays of the sender, and counting relays of the testing device are operated as previously described to check the operation of the senders in controlling district group selection. When relay 2209 has been deenergized a sufficient number of times to operate the No. 0' counting relay and the relay 2208 of the sender the fundamental circuit is opened as previously described and both relays 2209 and 100 deenergize. 75

The operation of the No. 0' counting relay closes a circuit for advancing sequence switch 2000 to position 6 which circuit may be traced from battery, winding of magnet 2000, upper left contact of cam 2001, lower contact of cam 1844, inner left back contacts of relay 2210, front contact of the No. 0' counting relay to ground. Since no office 80 selections are to be made and the translator has been set in a skip office position a second locking circuit is maintained for the counting relays extending from the front contact of the 0 counting relay over the lower contacts of cam 2017 to the contact of the arc of translator 2114 served by brush 2138 right contacts of cam 1855, lower right contact of cam 1849 to ground. This circuit is maintained through position 10. Sequence switch 2000 is advanced under the control 85 of its master cam and the 0' counting relay 90 to position 12. 95

The release of relay 100 opens the circuit of relay 510 as before described. Assuming that the correct number of pulses have been transmitted to satisfy the sender, a circuit will be completed from battery, winding of relay 511, back contact of relay 510, upper left contact of cam 514, upper left contact of the district group register cam 634, back contact of the No. 9 counting relay of the testing device, front contact of the Nos. 8, 7, 6, 5, 4, 3, 2, 1 and 0 counting relays to ground over conductor 108. The operation of relay 511 causes sequence switch 500 to advance to position 3. 105 110

Office brush register 615 is set in the skip office position 6. As soon as sequence switch 500 leaves position 2 1/2 a circuit is closed from battery through the winding of relay 511, back contact of relay 510, upper left contact of cam 525, lower contact of cam 637 to ground holding relay 511 operated to advance sequence switch 500 to position 5. 115

When sequence switch 500 leaves position 4 the above traced circuit is opened and relay 511 releases. Sequence switch 500 is advanced directly to position 6 in a circuit from battery, through the winding of sequence switch magnet 500, lower left contact of cam 505, upper left contact of cam 120 125 130

- 311, to ground. Sequence switch 200 is advanced from position 3 to position 5 in a circuit from battery, through the winding of sequence switch magnet 200. 5 upper left contact of cam 202, upper left contact of cam 506 to ground. It is then advanced to position 6 in a circuit from battery through the winding of sequence switch magnet 200, upper left contact of cam 209, 10 upper contacts of cam 528, right contacts of cam 329, left contact of interrupter 211, upper contact of cam 321 to ground. Relay 102 does not release when sequence switch 200 leaves position 3 but remains operated in 15 a circuit extending from battery, through its right winding and contact, contact of key 101, lower left contact of cam 215, upper contact of cam 637, to ground preventing the reestablishment of the fundamental 20 circuit until sequence switches 200 and 500 are in their correct positions.
- With switch 200 in position 6 the trunk guard relay 2211 is tested. The purpose of the trunk guard relay 2211 of the sender is 25 to prevent the advance of the sender to make incoming selections when the district or office selector picks an incoming selector at any time from trunk closure to the completion of talking at the incoming. During 30 this interval 24 volt battery is connected to the fundamental tip by the incoming selector circuit and sender relay 2211 should not operate until the incoming circuit is returned to normal.
- 35 A circuit is therefore, now closed from 24 volt battery, through high resistance 216 left contact of cam 204, upper right contact of cam 507, right contacts of cam 822, inner right contact of relay 1422, master selector 40 brush 1505 and its associated contact, sender selector brush 1525 and its associated contact, conductor 1818, back contact of relay 2002, right back contact of relay 1806, upper right contact of cam 1841, resistance 2016, 45 lower contact of cam 2014, winding of relay 2211, right winding of relay 2207 contact of relay 2208, winding of stepping relay 2209, lower left contact of cam 2004, upper contacts of cam 1847, brush 2123 of translator 50 2114, compensating resistance 2124, lower contact of cam 1846, outermost contact of relay 1845, conductor 1819, sender selector brush 1526 and associated contact, master selector brush 1506 and its associated contact, outer right contact of relay 1422, left contacts of cam 801, lower contact of cam 515, to ground. The ohmic resistance of 55 this circuit is such that a more severe non-operate test is applied to relay 2211 than required by service conditions.

If relay 2211 is properly adjusted that relay does not operate. If relay 2211 is out of adjustment so that it operates in this circuit, relay 2212 is operated as previously described in turn operating relay 2213, ad-

vancing sequence switch 2000 to its next position 14, in which a low resistance is substituted for high resistance 2016. This low resistance path at the sender extends from the upper right contact of cam 1841, lower 70 contact of cam 2206, right contact of cam 2003, right winding of relay 2207, and thence as previously traced.

Sequence switch 200 remains in position 6 for a period of one to two seconds after 75 which it is advanced to position 7 in a circuit from battery through the winding of sequence switch magnet 200, upper right contact of cam 209, left contact of interrupter 211, upper contact of cam 321 to 80 ground. Sequence switch 200 is then advanced to position 9 under the control of its master cam. While sequence switch 200 is passing through positions 7 and 8 relay 103 is substituted for resistance 216 in the 85 circuit previously traced for relay 2211. If relay 2211 operated as previously described advancing the sender to a low resistance position, relay 103 operates lighting lamp 114 in a circuit from battery, through that 90 lamp, front contact of relay 103, upper right and lower left contacts of cam 313, upper contact of cam 210 to ground. The operation of relay 103 also closes a circuit from battery through the winding of relay 115 to 95 the same ground. Relay 115 in operating closes a locking circuit for itself to ground at cam 210 and opens the fundamental circuit preventing the reoperation of relay 100. This delays the operation of the test circuit 100 so that the time alarm circuit previously described sounds an alarm to warn the attendant of the fact that the sender has not operated properly. The lighting of lamp 114 serves to indicate to the test man 105 that the trunk guard relay of the sender is out of adjustment.

When sequence switch 200 arrives in position 9, if relays 103, 115 and 2211 have not operated, the fundamental circuit is again 110 closed including relay 100, trunk guard relay 2211, stepping relay 2209 and high resistance 2016. Since the battery supplied to the winding of relay 100 is of higher voltage, relay 2211 operates in this circuit 115 causing in turn the operation of relays 2212 and 2213. Relay 100 does not operate in this circuit. The operation of relay 2213 closes a circuit from battery, winding of magnet 2000, lower right contact of cam 120 2012, inner right contact of relay 2213, upper contact of cam 1849 to ground, advancing sequence switch 2000 to position 14 in which position the fundamental circuit is extended from conductor 1818 over the back 125 contact of relay 2002, outer right contact of relay 1806, upper right contact of cam 1841, lower contact of cam 2206 lower right contact of cam 2003, through the right winding of relay 2207, back contact of relay 2208, 130

winding of stepping relay 2209, and thence as previously traced to ground.

Incoming brush and incoming group selections are now checked in succession, advancing impulse switch 200 one position after the check of each. The check switch 500 is also advanced one position at the completion of each check. Therefore at the time for checking final brush selection impulse switch 200 will be in position 11 and check switch 500 in position 8. Meanwhile the sender sequence switch 2000 has been advanced to position 18. In position 18 of the sender sequence switch a circuit is closed from battery, through the winding of sender control sequence switch 1800, upper left contact of cam 1840, lower contacts of cam 2019, contact of cam 2214 to ground. Sequence switch magnet 1800 is energized in this circuit to advance the sender control sequence switch to position 4.

The selections for final brush, final tens and final units are checked in the manner described for district brush selection and the impulse switch 200 is advanced to position 14 for checking the station hundreds selection. Check switch 500 is advanced to position 11 for this selection. During these selections the sender sequence switch 2000 is advanced to position 6 of its second rotation. At the completion of the checking of these selections, impulse switch 200 is in position 17, check switch 500 is in position 14 and sender sequence switch 2000 is in position 12.

In the establishment of a connection when selections are completed, battery and ground are reversed over the fundamental circuit to advance the sender for talking selection. To simulate this action on the part of the incoming selector the fundamental circuit is completed from battery through the winding of relay 100, back contact of the 10' counting relay, right contacts of cam 214, upper contact of cam 521, left contacts of cam 801, outer right contact of relay 1422, master selector brush 1506 and its associated contact, sender selector brush 1526 and its associated contact, conductor 1819, outer back contact of relay 1845, lower contact of cam 1846, compensating resistance 2127, translator brush 2128, upper contact of cam 2004, winding of stepping relay 2209, back contact of relay 2208, right winding of relay 2207, upper contact of cam 2003 upper left contact of cam 1841, outer back contact of relay 1806, contact of relay 2002, conductor 1818, sender selector brush 1525 and its associated contact, master selector brush 1505 and its associated contact, inner right contact of relay 1422, right contacts of cam 822, lower right contact of cam 507 to ground. The current flow in this circuit is in the proper direction to operate relay 2207 and relays 100, 2209 and 2207 operate. Re-

lay 2207 in operating locks in a circuit from battery, through its left winding, upper contacts of cam 2020 to ground at its left contact. Relay 2210 is energized in parallel with the left winding of relay 2207. The operation of relay 2210 closes a circuit from battery, contact of cam 1842, winding of the No. 0 counting relay, conductor 2021, outer right front contact of relay 2210, right contact of cam 2010, front contact of relay 2209, lower left contact of cam 2006 to ground energizing the No. 0 counting relay which operates and locks in a circuit including the winding of the No. 0' counting relay and its front contact to ground at cam 2011. The No. 0' counting relay does not operate being shunted.

In the ordinary operation of the sender the closure of the reversed fundamental circuit advances the incoming selector sequence switch to open the fundamental circuit and permit the operation of the No. 0' counting relay and of relay 2208. The closure of the reversed fundamental circuit in this position, operating relay 100, closes a circuit from battery, through the winding of sequence switch magnet 200, lower left contact of cam 209, right contact of cam 314, right contact of cam 205, innermost contact of relay 100 to ground. Magnet 200 energizes and advances the sequence switch to position 18. As switch 200 rotates from position 17 to position 18, the reversed fundamental circuit just traced is opened, releasing relay 2209 and opening the shunt around relays No. 0' and 2208 which relays operate. The operation of the No. 0' counting relay of the sender closes a circuit from battery through the windings of relays 1806 and 1845 in parallel, conductor 1810, strapped contacts of brush 1603 of the time measure switch 1610, conductor 1816, lower contact of cam 1850, right front contact of relay 2210, front contact of the No. 0' counting relay to ground. The operation of relay 1806 opens the circuit of relays 1807 and 503 in turn releasing relay 530. The release of relay 530 closes a circuit from battery, through the winding of magnet 500, upper left contact of cam 505, back contact of relays 530 and 502, right contact of cam 310, back contact of relay 511 to ground. The check sequence switch is advanced to position 15 in this circuit. With impulse switch 200 in position 18 and check switch 500 in position 15 sequence switch 800 is moved to position 18 in a circuit extending from battery, winding of magnet 800, lower right contact of cam 807, contacts of cam 212, lower left contact of cam 524 to ground.

In position 18 of switch 800 the direct current connection of the tip and ring conductors of the sender is opened and relay 1900 deenergized. The deenergization of relay 1900 opens the circuit of relay 1902,

which after an interval retracts its armatures in turn releasing relay 1903. The circuits are now in condition for checking talking selection. The operation of relay 1845.

- which after an interval retracts its armatures in turn releasing relay 1903. The circuits are now in condition for checking talking selection. The operation of relay 1845 previously described closes circuits for advancing the sender control and sender sequence switches which circuits may be traced from battery through the winding of sequence switch magnet 1800, upper right contact of cam 1851, middle front contact of relay 1845 to ground, in which circuit sequence switch 1800 is advanced to position 5; and from battery, through the winding of magnet 2000, lower left contact of cam 2012, inner front contact of relay 1845 to ground advancing this sequence switch to position 15. The advance of sequence switch 1800 from position 4 to position 5 opens the initial energizing circuits of relays 1845 and 1806, but these relays are held operated in a circuit from battery, through their windings and the inner right contact of relay 1806, lower left contact of cam 1848 to ground. The advance of sequence switch 2000 from position 14 to position 15 opens the locking circuit of relay 2207 and the circuit of relay 2210, releasing these relays. The release of relay 2210 closes a circuit for advancing sequence switch 2000 to position 16 which circuit may be traced through the winding of that magnet, upper right contact of cam 2001 to ground at the outer left contact of relay 2210.

With impulse switch 200 in position 18, check switch 500 in position 15, control switch 800 in position 18, sender control switch 1800 in position 5 and sender sequence switch 2000 in position 16 talking selection is checked. The fundamental circuit is closed as previously traced as far as conductor 1818 extending from thence over the contact of relay 2002, outer front contact of relay 1806, upper right contact of cam 2022, right winding of relay 2207, back contact of relay 2208, winding of relay 2209, resistance 2005, lower contact of cam 1839, terminal 9 and brush 2129 of register control switch 2100, which was advanced to this position after the completion of the setting of the stations registers, right back contact of relay 1902 to ground. Relays 100 and 2209 operate in this circuit and talking selection is now checked in the manner previously described for other selections; two sets of counting relays being operated. At the completion of this check, the check circuit is closed for relay 511 through the winding of that relay, back contact of relay 510, lower contact of cam 525, left contact of cam 315, right contact of cam 316 of talking selection register 300, back contact of the No. 2 counting relay of the testing device, front contact of the Nos. 1 and 0 counting relays to ground over conductor 108. The

operation of relay 511 closes an obvious circuit for advancing sequence switch 500 to position 16. With the check switch 500 in position 16 a circuit is closed from battery, through the winding of sequence switch magnet 200, upper left contact of cam 208, lower right and upper left contacts of cam 806, lower right contact of cam 506 to ground. Sequence switch 200 is advanced in this circuit to position 1 in which position a circuit is closed extending from battery, through the winding of relay 511, back contact of relay 510, lower right contact of cam 525, upper right contact of cam 203 to ground, advancing sequence switch 500 to position 17. When sequence switch 500 arrives in position 17, route control sequence switch 1300 is advanced to position 3 in a circuit extending from battery, through the winding of that magnet, left front contact of relay 1317, outer upper operated contact of key 1101, lower right contact of cam 524 to ground. As sequence switch 1300 moves from position 2 to position 3 the locking circuit of relay 1317 is opened and that circuit of relay 2207, relay releases. The release of relay 2210 permits the operation of relay 322 as previously described. In position 3 of route control switch 1300, the numerical control switch and the registers of the testing device are set in positions 2001 to 2004 to test the sender's ability to control a direct mechanical call without P. B. X. dialing.

With check switch 500 in position 17 a circuit is also completed for relay 1402 extending from battery, through the right winding of that relay, lower left contact of cam 1403, middle lower operated contact of key 1101, lower left contact of cam 529, lower contacts of cams 910, 911, 912, 618, lower right contact of cam 1217, contact of relay 301, contact of relay 302, outer upper operated contact of key 1101, lower right contact of cam 524 to ground. Relay 1402 operates and closes a circuit for relay 1404 from battery, winding of that relay, front contact of relay 1402, outer right contact of key 1401 to ground. The operation of relay 1404 closes a circuit from battery, through the winding of sequence switch magnet 500, lower left contact of cam 505, upper contacts of cam 1430, left front contact of relay 1404, left back contact of relay 1406 to ground. Sequence switch 500 advances to position 18 in this circuit. The operation of relay 1404 also disconnects ground from conductor 1831, permitting the sender to return to normal. When sequence switch 500 leaves position 17 the circuit previously traced for relay 1402 is opened but that relay remains operated through its left winding, right front contact of relay 1404, to ground on the test lead maintained by the sender during its restoration to normal. The

operation of relay 1404 opens the circuit of relay 1438 and that relay releases in turn releasing relays 1421 and 1422.

The restoration of the sender may be traced as follows: When sender control switch 1800 reached position 3 after the setting of the translators 2114 and 2115 and of class sequence switch 2200, a circuit was closed from ground, outer left contact of relay 2201, upper contact of cam 2215, upper left contact of cam 1852, upper right contact of cam 1853, brush 2107 of the A code register 2103 and its strapped contacts, back contact and winding of stepping magnet 2102, resistance 1906 and the left winding of relay 1905 in parallel to battery. Magnet 2102 is energized in this self-interrupting circuit to restore register 2103 to normal. When switch 2103 reaches normal the previously traced circuit is extended to brush 2150 of the B code register 2110 and its magnet to restore that register to normal. When register 2110 has been restored to normal and the sender control sequence switch 1800 has advanced to position 4 a circuit is established from ground, outer left back contact of relay 2201, upper contact of cam 2215, upper contacts of cam 1854, upper contacts of cam 2019, upper right contact of cam 1852, upper right contact of cam 1853, brush 2107 and its normal contact, brush 2150 and its normal contact, left contacts of cam 1855, brush 2131 of thousands register 2112 and its strapped contacts, back contact and winding of magnet 2132, resistance 1913 and the left winding of relay 1912 in parallel to battery. Magnet 2132 is energized in this self-interrupting circuit to restore the thousands register 2112 to normal. When switch 2112 reaches normal the above traced circuit is extended to brush 2133 and its strapped contacts, and magnet 2134 of hundreds register 2113 restoring that register to normal. When the hundreds register has been restored to normal and sequence switch 1800 is advanced to position 5, the above traced circuit is extended from brush 2133 and its normal contact, lower contacts of cam 1837, brush 2305 and its strapped off-normal contacts, back contact and winding of magnet 2306 of tens register 2300, resistance 1921 in parallel with the left winding of relay 1912 to battery. The tens register 2300 is restored in this circuit after which the restoring circuit is extended to brush 2307 of units register 2301 and successively to the registers 2302, 2303 and 2304. When register 2304 is restored to normal this circuit is extended through brush 2308 of stations hundreds register, brush 2309 of the stations tens register, and brush 2310 of the station units register to the No. 10 terminal of register control brush 2135 of register control switch 2100. When ground is re-

moved from conductor 1831 by the operation of relay 1404 as previously described relay 1802 operates in a circuit from battery, front contact of relay 1801, winding of relay 1802, outer left contact of relay 1804, back contact of relay 1801 to ground. Relay 1802 operates and locks to ground at its right contact and attracts its left armature, opening the circuit of relay 1803, which relay releases. The locking ground on the right armature of relay 1802 serves to maintain the sender busy during its restoration to normal. The release of relay 1803 completes a circuit from battery, through the right winding of relay 1905 and resistance 1909 in parallel, winding of stepping magnet 2105 of register control switch 2100 and its back contact, brush 2135 and its No. 9 terminal, left back contact of relay 1803 to ground, stepping register control switch 2100 to its No. 10 terminal.

It will be remembered that on the completion of the restoration of all the registers a circuit was extended from ground to the No. 10 terminal of brush 2135. With register control switch 2100 in position 10 this circuit is extended through brush 2135 and the back contact of magnet 2105 to the winding of magnet 2105 and battery in which circuit the register control switch in its turn is restored to normal. A circuit is thereupon closed from battery, through the winding of sender control sequence switch magnet 1800, lower right contact of cam 1840, brush 2129 of switch 2100 and its normal contact, right back contact of relay 1902 to ground. Sequence switch 1800 is advanced to position 6 in this circuit.

With switch 1800 in position 6 a circuit is closed from battery, winding of sender sequence switch magnet 2000, lower left contact of cam 2001 lower left contact of cam 1849 to ground. The sequence switch 2000 is advanced through position 18 to position 1 in this circuit.

With sequence switch 2000 in position 1 a circuit is closed from battery, winding of magnet 1800, left contact of cam 1851, lower contacts of cam 2401, upper contacts of cam 2023, brush 2129 and its normal contact, back contact of relay 1902 to ground.

It will be noted that this circuit is only completed when the sender sequence switch, relay call indicator impulse sequence switch and all the registers have been restored to normal. Sequence switch 1800 is advanced to position 7 which is one of its normal positions in this circuit. When sequence switch 1800 leaves position 6 the circuit of relay 1804 is opened and that relay releases in turn releasing relay 1805 and relay 1802. The release of relay 1802 removes ground from conductor 1831, releasing relay 1402 of the test circuit. The release of relay 1402

permits the release of relay 1404 and the re-operation of relays 1438, 1421 and 1422. As soon as relay 1404 closes its back contact ground is again connected to conductor 1831 to hold the sender busy while the next test is made.

As soon as sequence switch 500 reaches position 18 a circuit is closed from battery through the winding of sequence switch 10 magnet 800, upper right contact of cam 823, upper right contact of cam 524, to ground advancing sequence switch 800 to position 1. Sequence switch 800 is advanced to position 16 2 as previously described. When sequence switch 800 reaches position 2 sequence switch 500 is advanced to position 1 in a circuit from battery through the winding of the magnet, upper right contact of cam 505, upper right contact of cam 838 to ground. Sequence switch 1400 remains in position 4.

The sender testing device is now prepared to make the second one of the multiple tests of the sender. This second test is a check 25 of the ability of the sender to control the extension of a call to a subscriber's station in the office in which the call is initiated. The registers of the sender are positioned in the same manner as described for test 30 No. 1. The translator of the sender is again positioned in accordance with the setting of the code A and code B registers 2103 and 2110. The setting of the registers of the sender by the testing device is in the manner 35 described for test No. 1. The setting of the class switch 320 rotates the apparatus of the testing device through positions not required for this test. Upon completion of this test, the route control switch 1300 and 40 numerical switch 1200 are each advanced one position and the sender restored to normal for a third test.

Test No. 3 is a check of the operation of a sender when an incoming selector goes 45 to overflow. During a service connection when the incoming selector is associated with the overflow terminal, battery and ground are reversed with relation to the fundamental circuit, operating relay 2207 50 in the sender. The operation of relay 2207 causes the sender to advance, advancing the district for talking selections and both the sender and district are restored to normal. This test is made with the register switches 55 of the testing device in the same position as used for the previous test. The registers of the sender are set as described for a mechanical call, except that the stations registers are not set. For this test relay 60 809 is operated in a circuit from battery, through the winding of the relay, contacts of keys 1320 and 1321, lower left contact of cam 1305 to ground, hence low speed interrupter 700 is used in this test in place 65 of high speed interrupter 750. With switch

800 in position 12, the circuit previously described is again established for relay 1317 and that relay operates and locks, operating relay 1215. Sequence switch 800 is then advanced to position 13, in a circuit from 70 battery, through the winding of sequence switch magnet 800, upper left contact of cam 807, right contact of relay 1215 to ground. Sequence switch 800 continues to position 14 under the control of its master cam. The sequence switch is then advanced to position 17 in a circuit through its winding, lower right contact of cam 817, left back contact of relay 819 to ground. The 75 selections are checked as in the case of full mechanical calls until incoming group selection has been checked. Relay 511 is operated to advance sequence switch 500 to position 5. In position 5 relay 511 is re-operated in a circuit through its winding, 80 back contact of relay 510, upper right contact of cam 520, lower right contact of cam 330, to ground. Sequence switch 500 is advanced in this circuit to position 14. When sequence switch 500 leaves position 13 the 85 circuit of relay 511 is opened to cause its release. Sequence switch 200 is now rotated from position 5 to position 17 in a circuit from battery through winding of sequence switch magnet, lower right contact of cam 209, upper right contact of cam 506 to ground. With impulse switch 200 in position 17, battery and ground are reversed over the fundamental circuit as described 90 for incoming advance during a mechanical 95 call.

The reversal of battery and ground operates relay 2207 in the sender circuit to advance the sender for talking selection. The advance of the sender circuit opens the 105 actuating circuit for relay 503 in the testing device, in turn releasing relay 530 to advance sequence switch 500 to position 15. In position 15 a circuit is established to advance sequence switch 200 to position 18 110 and talking selection is checked in the manner previously described. Should relay 2207 in the sender fail to operate in response to the reversal of battery and ground, the sender does not advance to release relay 503, 115 and the automatic progress of the testing device is prevented and the alarm is sounded. Upon the completion of this test, the impulse switch 200, check switch 500, and control switch 800 are advanced as previously 120 described. Route control switch 1300 is advanced to position 5.

Tests Nos. 4, 5 and 6 direct calls to local operators and the numerical switches are not reset. The setting given the code registers 125 is translated into district brush, district group, office brush and office group selection, according to the location of trunks to operator's positions. The register switches in the testing circuit are cross connected ac- 130

cording to this location. These tests are similar to tests Nos. 1 and 2 with the exception of details of sender operation and it is thought unnecessary to describe them at length. Tests 5 and 6 differ in being applicable to non-coin and coin senders respectively. In testing a non-coin sender, route control switch 1300 is advanced through position 6 since relay 1317 is held locked in a circuit over its inner right front contact, inner back contact of relay 1323, upper left contact of cam 1318, to ground until sequence switch 1300 reaches position 8. Test No. 7 is not made during the majority 15 of routine tests and switches 1200 and 1300 are so cross connected as to pass position 8 corresponding thereto.

Tests Nos. 8 and 9 are similar in main characteristics to tests already described and 20 are not material to the disclosure of this invention. Therefore it is unnecessary to make a detailed description of these tests.

Tests 10 and 11 are of the sender relay call indicator mechanism and relate to calls 25 with or without stations respectively. These tests are made by setting the registers of the sender and are substantially the same as test 12.

Test 12 covers the ability of the sender to 30 control calls to a tandem relay call indicator office through which calls are extended to a second office.

Test No. 12—Tandem relay call indicator.

The route control switch 1300 and numerical switch 1200 are each advanced to position 13 to test the functioning of the sender during its regular operation for a tandem relay call indicator class of call. The sender 35 transmits pulses to display the wanted number on the call indicator lamps at the distant office. In this test after the registers of the senders are set, the sender transmits pulses to the testing device to check each digit for 40 which the registers are set. Register switches 350, 600, 615, 630, 645 and 660 are set in accordance with cross connections to the route control switch 1300 in position 13. The numerical registers 675, 900, 930 and class 45 switch 320 and talking selection register 300 are set in accordance with connections from those switches to cams in position 13 of numerical switch 1200. The registers and translator of the sender are set for a call 50 to a relay call indicator office in the manner described for a mechanical call. The class sequence switch 2200 is set in position 5 or 16 to control this particular type of call. High speed interrupter 750 is used for this 55 test since relay 809 is not operated. One revolution of interrupter 750 is made to set each register of the sender and the release of relay 812 after each revolution of the interrupter 750 positions the control sequence 60 switch 800 for the next revolution.

Sequence switch 800 thus rotates from position 2 to position 9 during the transmission of dial pulses to control the setting of the sender registers. Sequence switch 800 is then advanced to position 12 in a circuit 70 from battery, through the winding of that magnet, upper left contact of cam 837, upper right contact of cam 330 to ground. When sequence switch 800 leaves position 11, a circuit is established through the winding of 75 relay 1317, inner upper closed contact of key 1101, upper contacts of cam 818, upper left contact of cam 203 to ground. The operation of relay 1317 closes a circuit from battery, through the winding of relay 1215, 80 outer right contact of relay 1317 to ground. Relay 1215 operates and closes a circuit from battery, through the winding of sequence switch magnet 800, upper left contact of cam 807, right contact of relay 1215, to 85 ground. Sequence switch 800 is advanced to position 13 in this circuit and continues to position 14 under the control of its master cam.

The operation of the A and B code registers 2103 and 2110 in the sender circuit is the same as previously described for a mechanical call. The translator is set to control district, brush, district group, office brush and office group selection. The operation of the counting relays in the sender and sender relays of the testing device for checking pulses during selection are the same as previously described for a mechanical call. The check switch 500 upon the completion 95 of checking the office group selection is advanced to position 5 to establish the fundamental circuit for checking the relay call indicator pulses. With sequence switch 500 in position 5 and class sequence switch 350 in position 13 lamp 531 is lighted in a circuit from battery, upper right contact of cam 532, resistance 533, lamp 531, upper left contact of cam 330 to ground indicating that the 100 sender is being checked for tandem relay call indicator pulses.

A fundamental circuit is established which may be traced from battery, through resistance 2532, winding of relay 2521, left back contact of relay 2522, lower contacts of cam 331, upper right and lower left contacts of cam 806, upper left contact of cam 507, right contacts of cam 822, inner right contact of relay 1422, brush 1505 and its associated contact, brush 1525 and its associated contact, conductor 1818, back contact of relay 2002, right back contact of relay 1806, upper right contact of cam 1841, upper contact of cam 2206, upper right contact of cam 2014, winding of relay 2211, right winding of relay 2207, back contact of relay 2208, winding of relay 2209, upper contact of cam 2004, translator brush 2128, compensating resistance 2127, lower contact of cam 1846, 115 back contact of relay 1845, conductor 1819, 120 cam 1847, back contact of relay 1848, winding of relay 1849, upper contact of cam 1846, conductor 1819, back contact of relay 1845, conductor 1819, 125 cam 1847, back contact of relay 1848, winding of relay 1849, upper contact of cam 1846, conductor 1819, back contact of relay 1845, conductor 1819, 130 cam 1847, back contact of relay 1848, winding of relay 1849, upper contact of cam 1846, conductor 1819,

- brush 1526, and its corresponding contact, brush 1506 and its corresponding contact, outer right contact of relay 1422, left contacts of cam 811, lower contact of cam 521, 5 resistance 2531, right back contact of relay 2522 to ground. Relays 2211 and 2521 operate in this circuit. The operation of relay 2211 closes an obvious circuit for relay 2212 which in turn closes a circuit for relay 2213. 10 The operation of relay 2213 closes a circuit from battery through the winding of switch magnet 2000, lower right contact of cam 2012, inner right contact of relay 2213, upper contact of cam 1849 to ground. Sequence switch 2000 advances to position 14 in this circuit. The operated condition of relay 2213 in position 14 of switch 2000 also extends the fundamental circuit from the upper contact of cam 2206, over the outer 15 right front contact of relay 2213, upper right contact of cam 2014, through the winding of relay 2211, left winding of relay 2207, back contact of relay 2208, outer left front contact of relay 2213, translator brush 2128, and thence as previously traced to ground. The resistances of this circuit are chosen to produce as nearly as possible the most severe operating conditions for relay 2211. 20 The operation of relay 2521 closes a circuit for relay 2524. The operation of relay 2524 associates ground with the contacts of the register relays and lamp relays shown in Figs. 25, 26 and 27 for the purpose of establishing locking circuits when these relays are operated. 25 The operation of relay 2524 also closes a circuit from battery, through the winding of sequence switch magnet 200 which is in position 5, upper left contact of cam 209, outer left front contact of relay 2524 to ground, advancing sequence switch 200 to position 6. Switch 200 is now advanced to position 12 in a circuit from battery through the winding of the magnet, lower left contact of cam 208, lower left contact of cam 311 to ground. When sequence switch 200 reaches position 10, relay 2523 is operated in a circuit from battery, through its winding, outermost back contact of relay 2514, left back contact of relay 2513, upper contact of cam 217, upper contacts of cam 335, lower left contact of cam 506 to ground. The operation of relay 2523 supplies locking ground for other register and lamp relays and closes a circuit for relay 2522 extending from battery, winding of that relay, inner right contact of relay 2523, upper contacts of cam 335, lower left contact of cam 506 to ground. The operation of relay 2522 simulates the operation of an assignment key in a relay call indicator switch-board position and associates the fundamental circuit with polarized relays 2517, 2518 and marginal relay 2519. The last 30 three mentioned relays respond to the pulses of the sender impulse switch, Fig. 24, to operate the register and lamp relays. Relay 2211 releases upon the operation of relay 2522 since battery and ground have been removed from the fundamental circuit. The release of relay 2211 releases relay 2213. The operation of relay 2522 further opens the actuating circuit for relay 2521 to cause its release. 35 Since class sequence switch 2200 is in a position corresponding to a tandem relay call indicator call, having been set in position 5 (or 16) due to the translator setting, a circuit is established in position 12 of 80 sender sequence switch 2000 from battery, through the winding of relay 2402, lower right contact of cam 2216, back contact of relay 2201, upper right contact of cam 2028 to ground. Relay 2402 in operating closes a locking circuit for itself from battery through its winding and inner left contact, lower right contact of cam 2403, contacts of cam 2217, lower right contact of cam 1849 to ground. The operation of relay 2402 closes a circuit through the winding of relay 2404, outer right front contact of relay 2402 and thence as just traced to ground at cam 1849. Relay 2404 locks over its inner left front contact and upper contact of cam 2403 to the same ground. The operation of relay 2404 closes a circuit from battery, through the winding of impulser sequence switch magnet 2400, upper right contact of cam 2405, inner right front contact of cam 2404, upper contacts of cam 2218, middle left back contact of relay 2213, upper left contact of cam 2028 to ground. Sequence switch 2400 is advanced out of position 9 over the same circuit which it advanced out of position 1. 40 When sequence switch 2400 again reaches position 1 the circuit for moving it out of that position is still closed and it is started on a second revolution. 45 While sequence switch 2400 is making its first revolution and the first part of the second revolution pulses are transmitted over the fundamental circuit to operate the proper combinations of register and lamp relays shown in Figs. 25, 26 and 27. This fundamental circuit is the same as previously traced to the upper contact of cam 2206 and extends from thence over the outer right back contact of relay 2213, lower contacts of cam 2023, lower contacts of cam 2219, conductor 2406 and from thence to battery or ground, as determined by the setting of the registers in the successive positions of sequence switch 2400. The other side of the fundamental circuit may be traced from translator brush 2128, back over the outer left back contact of relay 2213, upper contacts of cam 2029, upper contacts of cam 2220, conductor 2407 and 50 55 60 65 70 75 80 85 90 95 100 105 110 115 120 125 130

thence to battery or ground as determined by the sender registers and switch 2400.

The sender registers for these tests have been set in the following positions:

5 Code A	Position 8
Code B	Position 5
Thousands	Position 4
Hundreds	Position 3
Tens	Position 2
10 Units	Position 1
Stations	Not set 0

The pulses corresponding to the different digits are set out in the following positions

15 of sequence switch 2400. Tandem tens positions 1 to 4, first revolution.

Tandem units positions 5 to 8, first revolution.

20 Stations positions 9 to 12, first revolution.

Thousands positions 13 to 16, first revolution.

25 Hundreds positions 17 to 20, first revolution.

Tens positions 1 to 4, second revolution.

Units positions 5 to 8, second revolution.

30 The method of sending out impulses is completely described in U. S. Patent No.

1,464,084 to A. E. Lundell, granted August

7, 1923.

These impulses consist of battery applied over the fundamental circuit in one direction or the other, in series with a greater

35 or less resistance in order to affect the polarized relays 2517, 2518 and marginal relay 2519 in accordance with the number to be transmitted. For example: while sequence switch 2400 is rotating from position 1 to

40 1 1/2 on its first revolution, ground is connected to conductor 2407 over the upper left contact of cam 2408, and the upper right contact of cam 2409; battery is connected to conductor 2406 through high resistance

45 2410, outer right front contact of relay 1903, right front contact of relay 2402, upper left contact of cam 2411, brush 2139 of A code register 2103 and its No. 8 terminal, contact of cam 2412, and outer right

50 front contact of relay 2404, producing a light positive pulse which is capable of operating polarized relay 2517 but which is not strong enough to operate relay 2519.

In position 2 to 2 1/2 of switch 2400 ground

55 is connected to conductor 2406 over the lower right contact of cam 2408, outer right front contact of relay 2404, and battery is connected to conductor 2407 through high resistance 2410, contact of cam 2413,

60 and right contact of cam 2409, and also through low resistance 2414, upper right contact of cam 2415, upper contact of cam 2416, No. 8 terminal and brush 2139 of A code register 2103, left contact of cam 2411,

65 right front contact of relay 2402, outer

right front contact of relay 1903, contact of cam 2413, and right contact of cam 2409. This produces a heavy pulse capable of operating relay 2518 and relay 2519.

In positions 3+3 1/2 ground is connected to conductor 2407 over the upper left contact of cam 2408, and the right contact of cam 2409. However, in position 3+3 1/2 of sequence switch 2400, the circuit from battery through high resistance 2410 is open and no battery is connected to conductor 2406 hence no relays are operated in the testing device.

In position 4+4 1/2 ground is connected to conductor 2406 over the lower right contact of cam 2408, and the outer right front contact of relay 2404, and battery is connected to conductor 2407 through high resistance 2410, contact of cam 2413, right contact of cam 2409 and through low resistance 2414, contact of cam 2415, upper contact of cam 2416, No. 8 terminal and brush 2139, left contact of cam 2411, right front contact of relay 2402, outer right front contact of relay 1903, contact of cam 2413, and the right contact of cam 2409, operating relays 2518 and 2519 of the testing device.

Circuits may be similarly traced for sending out actuating pulses to operate relays 2517, 2518 and 2519 in various combinations according to the setting of the sender registers. When sequence switch 2400 reaches position 9 1/2, the locking circuit of relay 2402 is opened and that relay releases. The circuit for the pulses is thereafter completed over the right back contact of relay 2402. Relay 2404 is held operated through the front contact of relay 2402 until sequence switch 2400 reaches position 8 1/2. It is thereupon held operated over the upper contact of cam 2403, to ground at cam 1849 until switch 2400 reaches position 2 1/2 of its second revolution. When sequence switch 2400 leaves position 2 1/2 relay 2404 releases. The succeeding positive pulses are fed to conductor 2406 over the upper contact of cam 2417 independent of the contact of relay 2404. When sequence switch 2400 leaves position 8 1/2 in its second revolution conductors 2406 and 2407 are disconnected from ground and battery, and the sequence switch completes its revolution without sending out pulses.

In the testing device when relay 2517 operates in response to the first pulse described, it completes a circuit from battery, through the winding of tandem tens register relay 2600, right back contact of transfer relay 2513, next to the outermost back contact of relay 2514, left back contact of relay 2516, front contact of relay 2517 to ground at the outer right contact of relay 2524. Relay 2600 operates and locks over its inner lower contact to ground at the inner right front contact of relay 2524.

When relays 2518 and 2519 operate in response to the second pulse a circuit is completed from battery, through the right winding of relay 2515, winding of relay 5 2516, right back contact of relay 2515, front contact of relay 2518 to ground at the outer right contact of relay 2524. Relay 2516 operates in this circuit but relay 2515 does not. Relay 2516 in operating closes a locking circuit for itself extending as previously traced through its winding, and thence through the left winding of relay 2515, outer right front contact of relay 2516 to ground at the outer right contact of relay 2524. The operation 10 of relay 2516 also closes a circuit from battery, through the winding of relay 2513, inner right back contact of relay 2512, middle back contact of relay 2514, inner right front contact of relay 2516, to ground at the outer right front contact of relay 2524. Relay 2513 operates in this circuit and closes a circuit through its winding and the winding of relay 2512, inner right contact of relay 2513, to ground at the outer left front contact of relay 2523. Relay 2512 does not operate at this time being shunted.

The operation of relay 2519, above described, closes a circuit from battery through the winding of relay 2601, inner 30 left back contact of relay 2512, next to the innermost back contact of relay 2514, outer left back contact of relay 2515, front contact of relay 2519 to ground at the outer left front contact of relay 2524. Relay 2601 35 operates and locks to ground through its inner lower contact, and the inner right contact of relay 2524.

When relay 2518 releases at the completion of the pulse, the shunt around the 40 winding of relay 2515 is opened and that relay operates in the locking circuit of relay 2516 and opens the energizing circuit of relay 2515. In response to the third pulse sent out, relays 2518 and 2519 are again operated. The operation of relay 2518 closes ground to the right armature of relay 2515 shunting relay 2516 and holding relay 2515 operated. Relay 2513 is held operated at this time over the inner left 50 front contact of relay 2515 in place of the inner right front contact of relay 2516. The operation of relay 2519 closes a circuit from battery, through the winding of relay 2603, outer left back contact of relay 2512, innermost back contact of relay 2514, outer 55 left front contact of relay 2515, contact of relay 2519 to ground at the outer right front contact of relay 2524. Relay 2603 operates and locks over its inner lower contact to ground at the inner right contact of relay 2524. The operation of relay 2603 60 closes a circuit from battery through the winding of relay 2712, outer lower contact of relay 2603, upper left contact of cam 218, upper contacts of cam 335, lower left con-

tact of cam 506 to ground. Relay 2712 operates and closes ground to certain of the lamps 2713 to 2722. Since relays 2712, 2600, 2601 and 2603 are operated a circuit is prepared from battery, through No. 8 lamp 70 2722, next to the outer front contact of relay 2712, outer lower front contact of relay 2600, upper front contact of relay 2601, back contact of relay 2602, outer right front contact of relay 2511, upper contact of cam 75 217 to ground at the lower left contact of cam 506, which is completed when relay 2511 operates. Sequence switch 2400 continues to send out pulses and operate the transfer relays of Fig. 25 and the lamp 80 register relays of Figs. 26 and 27. These relays lock and close circuits which become effective for checking the code pulses as soon as sequence switch 200 advances to the proper position. 85

The operation of relay 2603 also completes a circuit for relay 219 extending from battery through the winding of relay 219, upper right contact of cam 220, upper front contact of relay 2603, lower right contact 90 of cam 638, lower left contact of cam 639, outer lower front contact of relay 2600, upper front contact of relay 2601, upper back contact of relay 2602, and thence as previously traced to ground. The operation of relay 219 closes a circuit from battery through the winding of sequence switch magnet 200 to ground at the front contact of relay 219, advancing sequence switch 200 to position 11 in which position the tandem 100 units pulses are checked. As sequence switch 200 leaves position 10 the circuits for relays 219 and lamp 2722 are opened.

In position 10 of impulse switch 200 in which the tandem tens registration is 105 checked, a circuit is established to light a relay call indicator progress lamp and a match lamp indicating the setting of the register switch. Progress lamp 222, indicates that the tandem tens pulses are being 110 checked. The lighting of this lamp indicates that the code registers and translator of the sender have been correctly set, that the pulses were properly transmitted to the testing device by the sender to indicate the 115 number 8; that the sender is in condition to properly transmit relay call indicator pulses for the tandem tens digit of a service connection.

If a code other than that for the number 120 8 is transmitted, a lamp other than relay call indicator lamp 2722 is lighted and the progress of the testing device is arrested. The time alarm circuit shown in Fig. 11 is actuated to attract the attention of the test 125 man. The relay call indicator progress lamp 222 indicates that the tandem tens pulses were being checked, and the test man by referring to his chart discovers that the relay call indicator lamp 2722 should be lighted 130

to indicate No. 8. The test man knows what lamp has been lighted and now can trace the trouble in the sender revealed by the sender testing device.

5 The subsequent registrations and pulses are checked in the following positions of impulse switch 200.

Tandem units Position 11.
Stations Position 12.
10 Thousands Position 13.
Hundreds Position 14.
Tens Position 15.
Units Position 16.

15 The transfer relays for the various selections are as follows:

Tandem tens 2512, 2513.
Tandem units 2510, 2511.
20 Stations 2508, 2509.
Thousands 2506, 2507.
Hundreds 2504, 2505.
Tens 2502, 2503.
Units 2500, 2501.

25 The lamp relays for each registration are as follows:

Tandem tens 2600 to 2603.
Tandem units 2604 to 2607.
30 Stations 2708 to 2711.
Thousands 2608 to 2611.
Hundreds 2612 to 2615.
Tens 2700 to 2703.
Units 2704 to 2707.

35 The following tabulation indicates the operation of the various lamp relays to light the corresponding relay call indicator lamp of Fig. 27.

No.	Indications.	Lamp No.	Tandem tens.	Tandem units.	Stations	Thousands	Hundreds	Tens.	Units.
0		2716	normal	normal	normal	normal	normal	normal	normal
1		2718	2600	2604	2708	2608	2612	2700	2704
2		2721	2601	2605	2709	2609	2613	2701	2705
3		2719	2600	2604	2708	2608	2612	2700	2704
4		2714	2602	2606	2709	2609	2613	2701	2705
5		2715	2603	2607	2711	2611	2615	2703	2707
6		2717	2600	2604	2708	2608	2612	2700	2704
7		2720	2601	2605	2709	2609	2613	2701	2705
8		2722	2600	2604	2708	2608	2612	2700	2704
9		2713	2603	2607	2711	2611	2615	2703	2707

55 The check of the thousands digit differs slightly from that of the other digits but it is not believed to be necessary to describe this in detail.

At the completion of the check of the units pulses, sequence switch 200 is advanced to position 17. It is then advanced to position 18 in a circuit from battery through the winding of magnet 200, lower left contact of cam 209, lower left contact of cam 314 to ground. When sequence switch 200 reaches position 18 a circuit is

closed from battery, through the winding of relay 511, back contact of relay 510, upper right contact of cam 520, lower right contact of cam 210 to ground. Relay 511 operates and advances sequence switch 500 to position 14.

At the completion of this last test the route control switch is advanced into position 14 in a manner similar to that in which it was advanced from position 2 to position 75

3. It continues to advance to position 18 under the control of the master cam. When sequence switch 1300 reaches position 14 a circuit is completed for sequence switch 1200 from battery, through the winding of that magnet, upper contact of cam 1214, lower right contact of cam 1305 to ground, advancing sequence switch 1200 to position 1.

When sequence switch 1300 leaves position 13 relay 1317 releases.

In positions 14 to 18 of the route control switch 1300, with relay 1317 released, magnet 1400 is energized in a circuit from battery, through the winding of the magnet, upper left contact of cam 1431, upper normal contact of repeat key 1115, right back contact of relay 1116, lower contact of cam 1324, left back contact of relay 1317, outer upper operated contact of key 1101, lower right contact of cam 524 to ground.

Sequence switch 1400 advances to position 5 in this circuit. The sequence switch magnet 1400 is then energized in a circuit from battery, winding of the magnet, lower right

contact of cam 1405, back contact of relay 1414, left normal contact of key 1418, right back contact of relay 1409, lower right contact of cam 1428 to ground advancing the sequence switch to position 6.

The sequence switch is then advanced to position 7 in the circuit traced for advancing it from position 4 to position 5. Sequence switch 1400 is then moved into position 18 in the circuit previously traced for moving it out of position 5.

When sequence switch 1400 reaches position 18, the relay 1438 releases, in turn releasing relays 1422 and 1421. When the switch 1400 leaves position 17 ground is removed from the test lead, conductor 1831, permitting the sender to restore to normal.

With the sequence switch 1400 in position 18 the sender selector switch magnet 1527 and relay 1410 are energized in parallel circuits, that for magnet 1527 extending from battery, through the winding of that magnet, master selector brush 1513 and its associated contact, inner right operated contact of start key 1401, left back contact of relay 1103, to the upper left contact of cam 1412, that for relay 1410 extending from battery, resistance 1411, winding of relay 1410 to cam 1412 and from thence over the lower left contact of cam 1412, master selector brush 1503 and its first contact, master

selector brush 1511 and its associated contact to ground. A circuit is also established in shunt of relay 1410 from battery, through resistance 1411, lower contact of cam 1417, 5 selector brush 1502 and its associated contact, back contact of magnet 1527, master selector brush 1513 and thence as previously traced to ground at brush 1511. The stepping magnet energizes in the circuit previously traced opening the shunt circuit around the winding of relay 1410. Relay 1410 energizes and closes a circuit for advancing sequence switch 1400 to position 1. The advance of the sequence switch opens 10 the circuit of relay 1410 and stepping magnet 1527 advancing the sender selector 1520 to the terminals associated with the second sender.

With the sequence switch 1400 in position 1 route control sequence switch 1300 is moved to position 1 in a circuit from battery, through the winding of the magnet, lower contact of cam 1331, lowermost closed contact of multi-test key 1101, lower right 25 contact of cam 1437 to ground.

With the sequence switch 1400 in position 1 a circuit is also completed from battery, through the winding of relay 511, back contact of relay 510, right contact of cam 527, 30 upper left contact of cam 1428, to ground. Relay 511 operates and advances the check switch 500 out of position 17 in which it is at the completion of checking, into position 1.

When sequence switch 1400 reaches position 1 magnet 800 is energized from battery, through the winding of that magnet, lower left contact of cam 823, lower left contact of cam 1449, to ground. Sequence switch 40 800 is advanced in this circuit to position 1. As switch 800 passes from position 18 to position 1 the circuit of relay 1107 is opened restoring the time alarm circuit to normal as previously described.

Sequence switch 200 is also advanced to position 1 in a circuit from battery through the winding of the magnet, upper left contact of cam 208, upper left contact of cam 1449 to ground.

The cycle of operations which has been described is now repeated in connection with the second sender, after which the sender selector 1520 is advanced to the third sender, etc. When all the senders to which sender selector 1520 has access have been tested and switch 1400 is brought to position 1, relay 1402 is operated in a circuit from battery, through its right winding, lower right contact of cam 1403, outer left closed contact of key 1401, right contacts of cam 801, upper contacts of cam 501, lower contacts of cam 201, lower contact of cam 1304, left contact of cam 1201 to ground. Relay 1402 operates, in turn causing the operation of relay 60 1404 as previously described. Sequence

switch 1400 is advanced to position 2 opening the circuit of relays 1402 and 1404 which relays release.

When relay 104 releases a circuit is closed from battery, right winding of relay 1407, No. 21 terminal and brush 1521 of sender selector 1520, brush 1514 of master selector 1510, and its No. 1 terminal, right back contact of relay 1404, winding of relay 1438, right normal contact of key 1102, 75 upper right contact of cam 1449 to ground. Relay 1407 locks through its left winding and inner left contact to ground at the upper contact of cam 1409. The operation of relay 1407 closes a circuit for advancing sequence switch 1400 to position 3 extending from battery, through the magnet winding, right contacts of cam 1426, outer left front contact of relay 1407, upper contact of cam 1409 to ground. Sequence switch 1400 continues to rotate to position 4 under the control of its master cam. With relay 1407 operated, magnet 1527 is energized from battery, through its winding, terminal No. 1 and brush 1513 of master selector 1510, 80 lower contact of cam 1416, outer left front contact of relay 1407 to ground at the upper contact of cam 1409. A circuit is also closed for relay 1410 extending from battery, through resistance 1411, winding of relay 1410, right contact of cam 1412, outer left front contact of relay 1407 to ground. A circuit is also completed in parallel with relay 1410 extending from battery, through resistance 1411, lower contact of cam 1417, 90 brush 1502 and its first contact, back contact of magnet 1527, brush 1513 and its first contact, lower contact of cam 1416 to ground over the outer left front contact of relay 1407. Stepping magnet 1527 is energized in this circuit to step sender selector 1520 to normal. As soon as magnet 1527 opens its back contact relay 1410 is operated closing a circuit for advancing sequence switch 1400 to position 5. As sequence switch 1400 moves from position 4 to position 5 it opens the energizing circuits of relay 1410 and stepping magnet 1527. Sequence switch 1400 is immediately advanced to position 8 in a circuit from battery, right contacts of cam 1426, outer left front contact of relay 1407, to ground at the upper contact of cam 1409.

In position 5 1/4 to 6 of sequence switch 1400 master selector magnets 1501 and 1512 are energized. The circuit for magnet 1501 extends from battery, through its winding, left contact of cam 1416, outer left front contact of relay 1407 to ground; for magnet 1512 from battery through its winding, upper right contact of cam 1416 to ground over the outer left contact of relay 1407. Relay 1410 is also energized in a circuit from battery, through resistance 1411, winding of relay 1410, right contact of cam 1412 115 120 125 130

- to ground over the outer left contact of relay 1407. As before a circuit is maintained in shunt of the winding of relay 1410 extending from battery, through resistance 1411, upper contacts of cam 1417, back contacts of magnets 1501 and 1512 upper contacts of cam 1416, to ground over the outer left front contact of relay 1407. When both master selector magnets have opened their back contacts, relay 1410 is energized closing a circuit for advancing sequence switch 1400 to position 7 which opens the circuit of relay 1410 and stepping magnets 1501 and 1512 causing the master selectors 1500 and 1510 to step their brush assemblies to the next sender selector 1530. The sender selector 1530 is advanced to connect with the first sender to which it has access in the manner previously described.
- Any spare terminals which may remain after all the non-coin senders have been tested, will be strapped together to form a self-interrupting circuit similar to that shown with brush 1531 of switch 1540 to advance the selector over such terminals. Spare terminals on master selectors 1500 and 1510 are passed over by means of a similar self-interrupting circuit as will be seen by an inspection of the arcs served by brushes 1511 and 1508.

Coin senders.

Coin senders are connected to different sender selectors from those employed with non-coin lines or from those employed in connection with lines whose service is restricted.

In the drawings, sender selector 1540 is shown in Fig. 15 connected with coin senders. Fig. 17 shows that part of the sender which is used in testing for coin deposit and for collection or refund. A brief description will be given of the operation of the circuits of Fig. 17 which operate in the same general manner as those shown in the above mentioned patent to E. H. Mills.

Operation of coin circuit.

The setting of the registers of the sender (Figs. 17 to 23, inclusive) is the same as that previously described for the setting of the non-coin senders except that the circuit of relay 1900 extends over conductor 1832, inner right back contact of relay 1701, inner left back contact of relay 1702, inner left back contact of relay 1703, inner right back contact of relay 1704 and thence in the establishment of a call, over the ring conductor to the subscriber's dial, back over the tip conductor to the inner left back contact of relay 1704, outer left back contact of relay 1703, inner right back contact of relay 1702, inner left back contact of relay 1701 to conductor 1833. Relay 1804 operates as previously described and closes a circuit from battery, through the winding of relay 1705, middle right normal contact of relay 1705, brush 1706 of the time measure switch 1750 and its normal contact, conductor 1828, right front contact of relay 1804 to ground. Relay 1705 operates and locks through its middle alternate contact to ground on conductor 1828 independent of the time measure switch. With relay 1705 operated, as soon as interrupter 1707 closes its contact, stepping magnet 1700 is operated in a circuit from battery, winding of magnet 1700, contact of interrupter 1707, normal contact and brush 1708 of the time measure switch, left back contact of relay 1709, inner right contact of relay 1705, innermost right back contact of relay 1710, inner left contact of relay 1711 to ground. When the interrupter opens its contact, magnet 1700 releases stepping the time measure switch to terminal 1 in which position the above traced circuit is again closed, when the interrupter next closes its contact to step the switch to position 2. The circuit is also closed in position 2 when the interrupter again closes its contact and the switch is stepped to position 3.

If switch 2100 has not been stepped off normal by the time switch 1750 has reached position 3 a circuit is closed from battery, through sender monitor lamp 1712, left back contact of relay 1713, outer back contact of relay 1714, terminal 3 and brush 1708 of the time measure switch, outer left contact of relay 1709, inner right contact of relay 1705, innermost right back contact of relay 1710, inner left back contact of relay 1711 to ground, lighting the lamp to indicate to the sender monitor operator that a permanent signal condition exists.

If switch 2100 is stepped off normal a circuit is closed for relay 1717 from battery, through the left winding of that relay, conductor 1814, terminals 1 to 8 and brush 2130 of register control switch 2100 to ground. Relay 1717 operated closes a circuit for relay 1709 extending from battery, through the winding of relay 1709, brush 1716 of the time measure switch and terminals 1 to 4, strapped together, inner left front contact of relay 1717 and thence over the circuit previously traced to ground on brush 2137. The operation of relay 1709 closes a circuit from battery, winding of stepping magnet 1700 and its back contact, inner left contact of relay 1709 and thence as traced to ground at brush 2137. Magnet 1700 operates in this self-interrupting circuit to advance its brushes to terminal 5 at which time the circuit for relay 1709 and magnet 1700 is opened and relay 1709 releases. The switch is then advanced to position 8 in a circuit from battery, winding of magnet 1700, contact of interrupter 1707, contacts 5 to 7 and brush 1708, left back contact of relay 1709, inner right contact of relay 1705, innermost right

- back contact of relay 1710, inner left back contact of relay 1711 to ground. When the switch arrives in position 8, if switch 2100 is not advanced to position 9, the circuit for advancing the time measure switch is not closed and lamp 1712 is flashed in a circuit from battery, through lamp 1712, left back contact of relay 1713, outer right back contact of relay 1714, contact of interrupter 1719, No. 8 terminal and brush 1708 of the time measure switch, left back contact of relay 1709, inner right contact of relay 1705, innermost right back contact of relay 1710, inner left contact of relay 1711, to ground to indicate that dialing has not been completed. If switch 2100 has reached position 9 a circuit is closed from battery, through the winding of relay 1709, brush 1716 and contacts 5 to 8, conductor 1820, brush 2130 and its No. 9 contact to ground. Relay 1709 operates and closes a circuit from battery, winding of magnet 1700, inner left contact of relay 1709 and thence over the circuit traced for relay 1709 to ground at brush 2130. The operation of magnet 1700 steps the time measure switch to terminal 9. Relay 1709 is held operated in a circuit through its winding, brush 1716 and its terminals 9 to 12, back contact of relay 1718, innermost right back contact of relay 1710, inner left contact of relay 1711 to ground. Magnet 1700 is energized as before through the front contact of relay 1709 and its energizing circuit, to step the time measure switch to position 13 in which position relay 1709 is released. In positions 13 to 17 of the time measure switch a preliminary coin test is made. Relays 1713 and 1701 operate. The circuit for operating relay 1713 may be traced from battery, winding of that relay, left back contact of relay 1720, conductor 1835, back contact of relay 2024, conductor 1824, inner right contact of relay 1718, outer left contact of relay 1721, contacts 13 to 17 and brush 1706, conductor 1828, right contact of relay 1804 to ground. The circuit for relay 1701 is extended from battery, through the winding of that relay, outer right back contact of relay 1702 to conductor 1835 and thence as traced for relay 1713 to ground at the contact of relay 1804. It will be remembered that relay 1804 is operated as soon as relay 1803 is operated immediately upon the selection of an idle sender, and remains operated until the sender circuit is restored to normal. At the time of the closure of the above circuit the winding of relay 1720 and the left winding of relay 1722 are short circuited at the left back contact of relay 1722. The operation of relay 1713 closes a circuit from battery, through the winding of relay 1709, brush 1716 and terminal 13, inner right front contact of relay 1713, inner right contact of relay 1711 to ground. Relay 1709 operates and as before closes a circuit for magnet 1700 of the time measure switch, through its front contact to its operating ground, stepping the time measure switch to terminal 14 at which time the circuit of relay 1709 is opened. The switch is then stepped to position 17 in a circuit from battery, through the winding of magnet 1700, contact of interrupter 1707, terminals 14 to 16, brush 1708, left back contact of relay 1709, inner right contact of relay 1705, innermost right back contact of relay 1710, inner left contact of relay 1711 to ground. The operation of relay 1701 closes a circuit from battery, winding of relay 1723, outer left contact of relay 1701, terminal 14 and brush 1715 to ground. Relay 1723 is held operated when the time measure switch 1750 leaves terminal 14 in a circuit extending from battery, through the winding of relay 1723, outer left contact of relay 1701, outer right contact of relay 1723, outer left contact of relay 1721, terminals 13 to 17 and brush 1706, conductor 1828, right contact of relay 1804 to ground. The operation of relay 1701 also opens the dialing circuit through relay 1900 and repeating coil 1901. It closes a substitute circuit for relay 1900 from battery, through the winding of relay 1900, conductor 1832, outer right front contact of relay 1701, resistance 1724, conductor 1825, inner left front contact of relay 1903, to ground. It will be remembered that relay 1903 operates in response to the operation of relay 1900 as soon as the sender is selected. The operation of relay 1723 closes a circuit from battery through resistance 1725, inner left contact of relay 1723, right winding of relay 1726, inner right contact of relay 1720, inner left front contact of relay 1701, inner right contact of relay 1702, outer left contact of relay 1703, inner left back contact of relay 1704 to the tip conductor leading to a subscriber's substation. It also closes a circuit from source of negative 110 volt battery, outer left contact of relay 1723, left winding of relay 1726, outer right back contact of relay 1720, inner right front contact of relay 1701, inner left back contact of relay 1702, inner left back contact of relay 1703, inner right back contact of relay 1704 to the ring conductor and thence to the subscriber's substation. If the coin has been deposited at the subscriber's substation relay 1726 operates but it will not operate on a high resistance leak. Assuming that the coin has been deposited relay 1726 operates and locks in a circuit from 110 volt negative battery, outer left contact of relay 1723, left winding and left contact of relay 1726, outer right contact of relay 1711, conductor 1835, back contact of relay 2024, conductor 1824, inner right contact of relay 1718, outer left contact of relay 130

1721, contacts 13 to 17 and brush 1706, conductor 1828, right contact of relay 1804 to ground. The operation of relay 1726 closes a circuit from 48 volt battery, over its right contact, through the winding of relay 1720, conductor 1835 and back contact of relay 2024, conductor 1824, inner right contact of relay 1718, outer left contact of relay 1721, terminals 13 to 17 and brush 1706, conductor 1828 to ground at the right contact of relay 1804. Relay 1720 operates and opens the circuits for 48 volt battery and 110 volt battery through the windings of relay 1726. It also closes a circuit from 110 volt negative battery, outer left contact of relay 1723, resistance 1727, right winding of relay 1722, outer right front contact of relay 1720, inner right front contact of relay 1701, inner left back contact of relay 1702, inner left back contact of relay 1703, inner right back contact of relay 1704 to the ring conductor and thence to the subscriber's substation. In addition, it closes a circuit from ground at the right contact of relay 1804, over conductor 1828, brush 1706 and terminals 13 to 17 outer left contact of relay 1721, inner right contact of relay 1718, conductor 1824, left back contact of relay 2024, conductor 1835, left back contact of relay 1722, middle winding of relay 1722, inner right front contact of relay 1720, inner left front contact of relay 1701, inner right back contact of relay 1702, outer left back contact of relay 1703, inner left back contact of relay 1704, to the tip conductor, short circuiting the 48 volt battery which was connected from the right front contact of relay 1726 to one terminal of the middle winding of relay 1722. The operation of relay 1720 also opens the circuit previously traced through the winding of relay 1713 but relay 1713 being slow to release does not release until after relay 1722 has had time to operate. Relay 1722 operates if the subscriber's line is grounded thereby closing another circuit through the winding of relay 1713, inner right contact of relay 1709, front contact of relay 1722, conductor 1835, left back contact of relay 2024, conductor 1824, right back contact of relay 1718, outer left contact of relay 1721, contacts 13 to 17 and brush 1706, conductor 1828 to ground at the contact of relay 1804, preventing the release of relay 1713. However, if the subscriber's line is not grounded and the resistance is that of the coin and coin magnet, relay 1722 does not operate and relay 1713 releases. If relay 1713 is held operated so that switch 1750 enters position 17 before that relay releases, the coin lamp 1728 is lighted in a circuit through the left front contact of relay 1713, outer right back contact of relay 1714, contact of interrupter 1719, No. 17 terminal and brush 1708, outer left contact of relay 1709, inner right contact of relay 1705, innermost right back contact of relay 1710, inner left contact of relay 1711 to ground. The flashing of this lamp indicates to the operator either that no coin has been deposited by the subscriber (relay 1726 has not operated) or the line has been grounded accidentally, or in an effort to obtain a free call (relay 1722 operated). If either of these conditions arise, as soon as sender sequence switch 2000 arrives in position 3 in its second revolution after having completed final tens selection, relay 2002 operates in a circuit from battery, through its winding, right back contact of relay 1856, upper left contact of cam 2025, left contact of cam 1857, conductor 1812, outer right front contact of relay 1713 to ground. The operation of relay 2002 opens the fundamental circuit preventing final units selection, and the sender is released by the sender monitor operator in response to the lighting of lamp 1728. If the coin has been deposited relay 2002 is not operated, the sender proceeds with final units selection without interruption. As soon as relay 1713 releases a circuit is closed from battery, through the winding of relay 1709, brush 1716, and contacts Nos. 14 to 17, inclusive, right back contact of relay 1713, inner right contact of relay 1711 to ground, operating relay 1709 which closes an energizing circuit for stepping magnet 1700 in the manner previously described. Magnet 1700 steps switch 1750 to position 18 releasing relay 1709 and also relays 1726, 1720 and 1701. Switch 1750 is stepped from terminal 18 to terminal 21 in a circuit from battery, through the winding of magnet 1700, interrupter 1707, contacts 18 to 20, brush 1708, left back contact of relay 1709, inner right contact of relay 1705, innermost right contact of relay 1710, left back contact of relay 1711 to ground. If the sender has not been returned to normal when switch 1750 arrives at terminal 21 the sender lamp 1712 is flashed in a circuit from battery, through the lamp, left back contact of relay 1713, interrupter contact 1729, No. 21 terminal, brush 1708 and thence to ground as previously traced. When the sender returns to normal relay 1705 releases due to the opening of its circuit by the release of relay 1804. The release of relay 1705 closes a circuit from battery, through the winding of relay 1709, strapped off normal contacts and brush 1731, left back contact of relay 1705 to ground. Relay 1709 energizes and closes a circuit through magnet 1700 in the manner previously described in which circuit switch 1750 is restored to normal releasing relay 1709. This circuit is effective on the release of relay 1705 at any time. After the completion of the call, when the receiver is replaced on the switchhook of

the calling station, the district selector selects an idle sender for the purpose of collecting or returning the coin. Relays 1803, 1804, 1805, 1807 and 1809 operate as described in the establishment of the connection. Relay 1900 is not operated. The operation of relay 1804 establishes a circuit for relay 1705 through the winding and middle normal contact of relay 1705, normal contact 10 and brush 1806 of switch 1750, conductor 1828 to ground at the right contact of relay 1804. If the call was successful and the coin is to be collected the charge relay of the district is operated and ground is connected to 15 the fundamental ring, that is to conductor 1819, from where it is extended over the outer back contact of relay 1845, upper contact of cam 1846, conductor 1821, winding of coin collect relay 1732 to battery, operating 20 that relay. The operation of relay 1732 completes a circuit from battery, through the winding of relay 1856, conductor 1822, middle left front contact of relay 1732 and thence to ground in the district over conductor 1821 as previously described. 25 Relay 1721 operates in a circuit from battery, through resistance 1733, winding of relay 1721 and its left normal contact, conductor 1815, inner left contact of relay 1806, conductor 1811, next to the innermost right back contact of relay 1710, conductor 1826, inner right back contact of relay 1911, outermost left front contact of relay 1856 to 30 ground. Relay 1721 operates in this circuit and locks over its inner right front contact, conductor 1826, and thence to ground. Relay 1710 is operated from battery, left winding of relay 1710, outer right contact of relay 1705, normal contact of brush 1731 of 35 switch 1750, left front contact of relay 1705, middle right contact of relay 1721, conductor 1815, inner left contact of relay 1806, and thence to ground as previously traced. Relay 1710 operated, locks through its left 40 winding and next to the innermost front contact to ground over conductor 1826 as just traced. The operation of relay 1710 closes a circuit for relay 1709 extending from battery, winding of relay 1709, brush 1730 and its normal terminal, innermost right 45 front contact of relay 1710, inner left back contact of relay 1711 to ground. The operation of relay 1709 closes a circuit for stepping magnet 1700 in the manner previously described over the left front contact of relay 1709 to the operating ground of that relay. Magnet 1700 steps switch 1750 to terminal 1 and then to terminal 10 in this circuit since 50 the normal terminal and the first nine off normal terminals are strapped together. 55 When switch 1750 arrives in position 10 relay 1709 releases. Relay 1703 is operated in positions 10 to 12 of switch 1700 in a circuit extending from battery, through the winding of that relay, terminals 10 to 12, 60 brush 1730, innermost right front contact of relay 1710, inner left contact of relay 1711 to ground. The operation of relay 1703 closes a circuit for relay 1723 from battery, through the winding of that relay, outer 70 right contact of relay 1703, terminals 9, 10 and 11 and brush 1715 to ground. It also closes a circuit for relay 1714 from battery, through the winding of relay 1714, inner right contact of relay 1703 to ground. The 75 operation of relay 1723 closes a circuit from 110 volt positive coin battery, inner right contact of relay 1723, winding of relay 1734, inner left contact of relay 1732 and thence in parallel over the inner left front contact 80 of relay 1703, inner right back contact of relay 1704, over the ring conductor to the subscriber's substation and also over the outer left front contact of relay 1703, inner right back contact of relay 1704, over the 85 tip conductor to the subscriber's substation. If a coin is present at the subscriber's substation relay 1734 operates closing an obvious circuit for relay 1717, which locks through its right winding and inner right 90 contact, over the outer right and inner left contact of relay 1721 to ground over conductor 1826. Relay 1717 opens an alarm circuit to be described subsequently. 95 The operation of relay 1714 closes a circuit from battery, winding of stepping magnet 1700, outer right front contact of relay 1714, contact of interrupter 1719, middle right contact of relay 1714, contacts 5 to 13 and brush 1706 of switch 1750, conductor 100 1828 to ground at the right contact of relay 1804. As the interrupter makes and breaks its contact, brush 1700 operates and releases, stepping switch 1750 to terminal 13. When switch 1750 leaves terminal 12, relay 1703 is released in turn releasing relays 1723 and 1714. The circuit of relay 1703 is maintained through position 12 in order to hold condenser 1735 and resistance 1736 connected to the line until after the coin magnet in the coin box has had time to discharge 105 in order to protect the multiple bank. The release of relay 1714 opens the circuit through magnet 1700, stopping the switch on terminal 13. 110 In position 13 a circuit is closed from battery, through the winding of relay 1702, outermost right contact of relay 1710, terminal 13 and brush 1715 to ground. Relay 1702 is maintained operated in positions 14 115 to 17 over terminals 13 to 17 and brush 1706, conductor 1828, to ground at the right contact of relay 1804. The operation of relay 1702 connects battery through the windings of relay 1737, through the inner front contacts of relay 1702, left back contacts of relay 1703, inner back contacts of relay 1704, over the tip and ring conductors to the subscriber's substation. If the coin has not 120 been collected or returned at this time or if 125 130

either side of the line is grounded in some other way, the differentially wound relay 1737 operates, in turn operating relay 1713. The operation of relay 1713 closes a circuit for relay 1709, from battery, through the winding of relay 1709, brush 1716 and its No. 13 terminal inner right contact of relay 1713, inner right back contact of relay 1711 to ground. The operation of relay 1709 10 closes the usual circuit for operating the stepping magnet 1700 and switch 1750 is stepped to its No. 14 terminal. Relay 1709 is held operated through terminals 14 to 16 inclusive of brush 1730, innermost right front contact of relay 1710, inner left contact of relay 1711 to ground causing the operation of magnet 1700 to step the switch to terminal 17 in which position relay 1709 releases. The operated condition of relay 1713 20 opens the circuit for stepping the switch from terminal 17 and closes a circuit for lamp 1728 from battery, through the lamp, left front contact of relay 1713, upper contact of interrupter 1729, No. 17 terminal and brush 1730, innermost right front contact of relay 1710, inner left contact of relay 1711 to ground. The lamp 1728 flashes in this circuit indicating that the coin has not been collected or that there 30 is some other ground on the line.

If, when time measure switch 1750 makes final coin test in position 13 the coin has been collected and no ground is on the line the switch is stepped from terminal 13 to terminal 14 in a circuit from battery, through magnet 1700, contact of interrupter 1738, outer left contact of relay 1702, No. 13 terminal and brush 1730, innermost right front contact of relay 1710, inner back contact of relay 1711 to ground. In position 40 14 relay 1709 is operated in a circuit from battery, through the winding of relay 1709, terminals 14 to 16 and brush 1730, innermost right front contact of relay 1710, inner left contact of relay 1711 to ground. The operation of relay 1709 closes the usual operating circuit for magnet 1700 and switch 1750 is stepped to position 17 whereupon relay 1709 deenergizes.

50 Since we have assumed that the coin has been properly collected and the line is clear, relay 1713 is deenergized when the switch reaches position 17, the circuit of relay 1709 is extended over terminal 17 and brush 1716 through the inner right back contact of relay 1713 and the inner right contact of relay 1711 to ground and the switch is advanced to position 18. With switch 1750 in position 18 ground is connected from the right contact of relay 1804, over conductor 1828, brush 1706 and terminals 18 to 21, next to the outermost right contact of relay 1710, conductor 1813, outer left contact of relay 1806 to conductor 1817 releasing a relay in 60 the district selector circuit and returning

the district selector to normal. As the district selector is returned to normal, ground is disconnected from conductor 1819 permitting relay 1732 to release. Ground is also removed from conductor 1831 permitting relay 1802 to operate and release relay 1803. The release of relay 1803 releases relays 1804, 1805, 1807, 1809, 1856 and 1705. The release of relay 1856 releases relays 1710 and 1721, also relay 1717 if that relay is operated. The release of relay 1705 closes a circuit from battery, through the winding of relay 1709, off-normal contacts and brush 1731, left back contact of relay 1705 to ground. Relay 1709 closes the usual circuit 80 for stepping magnet 1700 to advance the time measure switch to normal at which time the circuit for relay 1709 and magnet 1700 is opened. The release of relay 1805 opens the circuit of relay 1802 and since none of the sequence switches or registers have been stepped off normal the sender is in condition to be selected for use with other calls.

If the connection was not successfully established and a coin is to be returned the charge relay of the district is not operated and hence does not connect ground to conductor 1818 and in turn relay 1732 is not operated. The time measure and sender circuits function as just described except that with switch 1750 engaging terminals 10 to 12 negative coin battery is connected to the tip and ring of the line over the outer left contact of relay 1723, inner right back contact of relay 1732, left front contacts of relay 1703, inner back contacts of relay 1704 and thence over the tip and ring to the subscriber's substation. The switch is then stepped to terminal 17 as described for coin 165 collect operation.

In position 17 if the coin has not been refunded or there is a ground on the line the coin lamp 1728 is lighted in a circuit through that lamp, front contact of relay 1713, outer left back contact of relay 1732, terminal 17 and brush 1730, innermost right front contact of relay 1710, inner left contact of relay 1711 to ground.

In the case of calls originating at coin stations for which no charge is to be made, such as calls to operators' positions and to the telephone company's business office, at the completion of the setting of the translator a circuit is closed for relay 2024. This circuit is completed from battery through the right winding of relay 2024, contacts of the translator are served by brush 2138 which are reserved for such calls, right contacts of cam 1855, lower right contact of cam 1849 to ground. Relay 2024 operated locks through its inner right contact to ground at cam 1849. The time measure switch will function as described until it steps to terminal 13 for a preliminary coin test. The 130

circuit for relays 1713 and 1701 which extend over the back contact of relay 2024 is opened at this time and these relays cannot be operated.

- 5 Relay 1709 operates in a circuit through brush 1716, terminal 13, conductor 1836, left front contact of relay 2024, conductor 1824, inner right contact of relay 1718, outer left contact of relay 1721, terminals 13 to 17 and 10 brush 1706, conductor 1828 to ground at the right contact of relay 1804. The operation of relay 1709 causes magnet 1700 to step the switch to terminal 14. Relay 1709 is held 15 operated through its winding, brush 1716 and contacts 14 to 17, right back contact of relay 1713, inner right contact of relay 1711 to ground, so that switch 1750 is stepped to terminal 18 releasing relay 1709. Further 20 release of the sender and time measure circuit is as previously described.

Test of coin senders.

- Assume that the master selectors 1500 and 1510 have been advanced to connect with 25 sender selector 1540 and that sender selector 1540 has been positioned on one of the coin senders. The testing device will proceed to make the same series of tests on the coin senders as on the non-coin senders. When 30 master selectors 1500 and 1510 connect with sender selector 1540 and sequence switch 1400 reaches position 2, a circuit is closed from battery, winding of relay 1303 brush 1509, and its associated contact, upper contact of cam 1409 to ground. The operation 35 of relay 1303 closes a circuit from battery through the winding of relay 1414, a terminal of cross connecting rack 1819 to ground at the outer left contact of relay 40 1303. Preliminary coin test is not made in connection with all of the test units. When class switch 320 is set in positions 1, 2, 9 to 15, the operation of relay 1414 closes a circuit when sequence switch 1400 reaches position 45 4, from battery, through the winding of relay 819, contact of key 824, contact of cam 317, upper contact of cam 1432, front contact of relay 1414, left contact of key 1418 right back contact of relay 1407 to ground. The operation of relay 1303 also 50 closes circuits for controlling the setting of the registers on calls to the zero operator.

- The tests proceed as for a non-coin call. When the registers of the testing device 55 have all been set, the control sequence switch 800 is advanced to position 13 due to the operation of relay 1317 and then to position 14. Since the sender now under test is a coin sender and relay 819 is operated 60 no circuit is closed for advancing sequence switch 800 out of position 14 and sequence switch 800 remains in position 14 while impulse switch 200 and check switch 500 check 65 selections including final tens selection. On the completion of final tens selection, check

switch 500 is advanced to position 10 and impulse switch 200 is advanced to position 13. Relay 100 does not operate at this time since its circuit is open at the lower contact of cam 825, through which its circuit is extended in position 10 by check 70 switch 500.

In position 13 of impulse switch 200 and position 14 of control switch 800 a circuit is established from battery, through the winding of magnet 800, upper right contact of cam 817, lower left contact of cam 335, lower left contact of cam 210, to ground. Sequence switch 800 is advanced to position 15 in this circuit. In positions 15 and 16 80 of switch 800 a circuit is prepared from battery through the winding of relay 839, right front contact of relay 819, upper left contact of cam 825, lower contact of cam 507, right contacts of cam 822, inner right contact of relay 1422, master selector brush 1505 and its associated contact, sender selector brush 1516 and its associated contact, conductor 1818, back contact of relay 2002, right back contact of relay 1806, upper left 90 contact of cam 1841, upper left contact of cam 2003, right winding of relay 2207, contact of relay 2208, winding of relay 2209, lower right contact of cam 2004, lower contacts of cam 1847, brush 2128 of translator 95 2114, compensating resistance 2127, lower contact of cam 1846, right back contact of relay 1845, conductor 1819, sender selector brush 1517 and its associated contact, master selector brush 1506 and its associated contact, outer right contact of relay 1422, left contacts of cam 801, lower contacts of cam 515, resistance 534 to ground, which is completed when the sender sequence switch advances to position 3. 105

Also in position 15 ground is connected to the tip and ring conductors through approximately 4000 ohms resistance to test the operating condition of relay 1726. These circuits may be traced from ground through resistances 827 and 828, lower left contact of cam 829, inner right front contact of relay 819, and from thence over the contact of cam 802, conductor 1003, lower contacts of cam 1314, outer upper normal 110 contact of key 1313, conductor 1004, inner left contact of relay 1422 to the tip conductor, and through the right winding of repeating coil 820, upper contact of cam 327, conductor 1002, inner upper normal contact of key 1313, lower contact of cam 1312 to conductor 1001, upper contact of cam 804, front contact of relay 1422 to the ring conductor. Substation 1315 and high resistance 1326 are bridged across the 115 repeating coil as previously described.

It will be remembered that while the time measure circuit of Fig. 17 is advanced from positions 13 to 17 certain operations take 120 place which lead to the connection of nega- 125

- tive 110 volt battery, over the outer left contact of relay 1723, through the left winding of relay 1726, outer right back contact of relay 1720, inner right front contact of relay 1701, inner left back contact of relay 1702, inner left back contact of relay 1703, inner right back contact of relay 1704 to the ring conductor, and that a circuit is also closed from battery through resistance 1725, inner left back contact of relay 1723, right winding of relay 1726, inner right contact of relay 1720, inner left front contact of relay 1721, inner right contact of relay 1712, outer left contact of relay 1703, inner left back contact of relay 1704 to the tip conductor. Relay 1726 should be so adjusted as to fail to operate when the receiver is off the switchhook and a moderately high resistance leak exists but should operate through the 1000 ohms resistance on coin magnets and coin.

Relay 1726 should not operate in this circuit through resistances 827 and 828, preventing the closure of the fundamental circuit at the contact of relay 2002. If the fundamental circuit previously described is falsely closed, relay 839 operates closing a circuit from battery through the winding of relay 1117, lower contacts of cam 1444, contact of relay 829 to ground. Relay 1117 operates and locks through its right front contact, lower left contact of cam 1437 to ground. The operation of relay 1117 prevents the advance of sequence switch 800 and the completion of the test. After a proper length of time has elapsed time measure switch 1100 sounds an alarm.

If the fundamental circuit is not closed and relay 839 does not operate a circuit is closed from battery through the right winding of relay 832, lower contacts of cam 818, upper contact of interrupter 826, back contact of relay 1117, back contact of relay 1118, left normal contact of key 1418, right back contact of relay 1407, lower right contact of cam 1428 to ground as soon as interrupter 826 closes that contact. Relay 832 operates and locks through its right contact to ground at the lower contact of cam 838. The operation of relay 832 closes a circuit from battery through the winding of sequence switch magnet 800, lower right contact of cam 817, middle right contact of relay 832, lower contact of interrupter 826, to ground as previously traced, advancing sequence switch 800 to position 16. When sequence switch 800 leaves position 15 the locking circuit of relay 832 is opened and that relay releases. In position 16 relay 832 is again operated as previously described and again advances sequence switch 800 to position 17.

In position 17 ground is connected through resistance 827, back contact of relay 840, lower right contact of cam 829, inner

right front contact of relay 819 and thence as previously traced to the tip and ring conductors and the windings of relay 726. Relay 726 operates in this circuit advancing the time measure switch and closing the fundamental circuit for the final units selection. Sequence switch 800 now being in position 17 the fundamental circuit is extended over the lower contact of cam 825 to relay 100 as usual. 75

In connection with certain tests, relay 1722 is tested instead of relay 1726. These tests are Nos. 2, 10 and 12. Therefore, when the route control switch 1300 is set in positions 3, 11 or 13 relay 840 is operated in a circuit from battery, through the winding of that relay, left contacts of cam 1327 and thence over the circuit previously traced for relay 819 to ground. With sequence switch 200 in position 13 in connection with a mechanical test, the fundamental circuit is held open until the preliminary coin test is made. Sequence switch 800 is advanced from position 14 to position 15 as previously described. 80

In position 15 the tip and ring conductors are connected to ground through resistances 827 and 828 as previously described and sequence switch 800 is advanced to position 16. With sequence switch 800 in position 16 ground is connected over the contact of relay 840, upper right contact of cam 829, inner right front contact of relay 819 and thence as previously described to the tip conductor operating relay 1726. 85

The operation of relay 1726 closes a circuit from 48 volt battery, over its right contact, through winding of relay 1720, conductor 1835, back contact of relay 2024, conductor 1824, inner right contact of relay 1718, outer left contact of relay 1721, terminals 13 to 17 and brush 1706, conductor 1828 to ground on the right contact of relay 1804. The operation of relay 1720 opens the circuit from 48 volt battery and 110 volt battery through the windings of relay 1726. It also closes a circuit from 110 volt negative battery, outer contact of relay 1723, resistance 1727, right winding of relay 1722, outer right front contact of relay 1720, inner right front contact of relay 1701, inner left back contact of relay 1702, inner left back contact of relay 1703, inner right back contact of relay 1704 to the ring conductor. 90

In addition it closes a circuit from ground at the right contact of relay 1804, over conductor 1828, brush 1706 and terminals 13 to 17, outer left contact of relay 1721, inner right contact of relay 1718, conductor 1824, left back contact of relay 2024, conductor 1835, left back contact of relay 1722, middle winding of relay 1722, inner right front contact of relay 1720, inner left front contact of relay 1701, inner right back contact of relay 1702, outer left back contact of relay 1703, inner left back contact of relay 1704 to the tip conductor, short 95

- circuiting the 48 volt battery which was connected from the right front contact of relay 1726 to one terminal of the middle winding of relay 1722. The direct ground which operates relay 1726 simulates a trouble condition on a call or an attempt to obtain a free call and causes the operation of relay 1722. The operation of relay 1722 causes a signal to be given to the sender monitor operator indicating this condition. Sequence switch 800 advances to position 17 as previously described. As the switch leaves position 16 the line circuit is opened and as the switch passes position 16 $\frac{1}{2}$, 110 volt negative battery, through a special lamp 842, is connected over the contact of relay 840, contact of cam 843, to the tip of the line neutralizing the 110 volt negative battery already connected therewith and releasing relay 1722.
- In position 17 ground is connected through low resistance 844, over the left front contact of relay 840, lower right contact of cam 829 to the tip conductor, as a non-operate test for relay 1722. If relay 1722 does not operate the fundamental circuit is closed through to permit the next selection as for the previous case.
- The testing device now proceeds to test the accuracy of the sender to control the remainder of the selections. Since multi-test key 1101 is operated the sender will be tested for its control of the completion of the various types of calls and route control switch 1300 will be advanced to position 18 before testing the sender for its ability to control coin collection or refund. After the completion of the multi-test, sequence switch 1400 is advanced to position 5 as previously described. Due to the operation of relay 1414 the circuit traced in connection with the test of non-coin senders is opened, sequence switch 1400 cannot leave position 5 and the tip and ring are held connected through the artificial subscriber's line shown in Fig. 13.
- In position 5 of sequence switch 1400 a circuit is closed from battery, through the right winding of relay 1402, upper contact of cam 1403, front contact of relay 1414, left normal contact of key 1418 right back contact of relay 1407, lower right contact of cam 1428 to ground. Relay 1402 operates and closes a circuit from battery, through the winding of relay 1404, contact of relay 1402, outer right closed contact of key 1401 to ground. The operation of relay 1404 opens the circuit of relay 1803 and permits the operation of relay 1802 to bring about the restoration of the sender. It also closes a circuit from battery, through the winding of sequence switch magnet 1400, lower left contact of cam 1405, inner left front contact of relay 1404, left back contact of relay 1406 to ground advancing the sequence switch to position 6. When sequence switch 1400 leaves position 5 the operating circuit of relay 1402 is opened but relay 1402 remains energized over the right front contact of relay 1404 to ground at the sender while it is restoring to normal. Sequence switch 1400 is then advanced to position 7 in a circuit from battery, through its winding, upper left contact of cam 1431, upper normal contact of key 1115, right back contact of relay 1116, lower contact of cam 1324, left back contact of relay 1317, upper operated contact of key 1101, lower right contact of cam 524 to ground. In positions 7 and 8 of sequence switch 1400 a circuit is closed from battery, lamp 1120, upper left contact of cam 1454, to ground.
- When the sender is restored to normal it removes the busy ground from conductor 1831 permitting the release of relay 1402 which in turn permits the release of relay 1404. When relay 1404 closes its back contact it connects ground from the upper right contact of cam 1449, right contact of key 1102, winding of relay 1438, right armature and back contact of relay 1404 to conductor 1831, to again render the sender busy. This simulates the dismissal of the sender and its reselection for the purpose of coin collection or refund. In position 7 no ground is connected to the fundamental ring, which may be identified as conductor 1819, and hence the sender is tested for the return of a coin. Relays 1803, 1804, 1805, 1807 and 1705 operate as previously described.
- Relay 1900 is connected through the upper contact of cam 1424 to ground through relay 1121 which has an extremely high resistance and simulates a high resistance leak to ground and therefore relay 1900 should not operate. If it does operate, due to faulty adjustment, the sender control sequence switch is advanced, but since no dialing follows, the sender operation is blocked and the sender and test circuit time alarm circuits are permitted to sound an alarm. The tip conductor is connected through the upper contact of cam 1423, resistances 1128 and 1129, windings of polarized relay 1122 to ground at the upper left contact of cam 1437, which simulates the coin box and coin of the subscriber's substation with the receiver on the hook. The operation of relays 1807 and 1803 closes a circuit from battery, through the winding of relay 1856, left back contact of relay 1902, which is not operated since relay 1900 is not operated, outer right contact of relay 1807, outer right back contact of relay 1903, back contact of relay 1900, left front contact of relay 1803 to ground. Relay 1856 operates and locks over its innermost left contact directly to ground at the front contact of relay 1803. The operation of relay 1856 closes a circuit from battery, winding and left normal contact of relay 1721, conductor 1815, inner left contact of relay 1806, conductor 1811, next to

the innermost back contact of relay 1710, conductor 1826, inner right back contact of relay 1911, to ground on the outermost left contact of relay 1856. Relay 1721 operates and causes the operation of relay 1710 as previously described. The operation of relay 1710 closes a circuit from battery, through the winding of relay 1709, normal and first nine contacts and brush 1730 of switch 1750, innermost right front contact of relay 1710, inner left contact of relay 1711 to ground. Relay 1709 closes a circuit for stepping magnet 1700 as previously described, to step the switch to terminal 10. Relay 1703 is operated through strapped terminals 10 to 12 and brush 1730 as previously described. The operation of relay 1703 causes the operation of relays 1723 and 1714. The operation of relay 1703 disconnects the tip and ring conductors from the sender and connects them in parallel over a back contact of relay 1732 to the outer left contact of relay 1723. The operation of relay 1723 connects the 110 volt negative battery over the tip and ring conductors to polarized relay 1122 and relay 1121 which relays operate closing a circuit from battery, through the winding of relay 1118, contact of relay 1122, contact of relay 1121 to ground. The operation of relay 1118 closes a circuit from battery, through the winding of sequence switch magnet 1400, lower left contact of cam 1431, inner left front contact of relay 1118, left normal contact of key 1418, right back contact of key 1407, lower right contact of cam 1428 to ground, advancing sequence switch 1400 to position 8.

The operation of relay 1118 also extends the circuit of relay 1807 over its outer left front contact, upper left contact of cam 526 to the windings of relays 502 and 503 independent of class switch cam 821. The sender now tests the line to ascertain whether the coin has been returned by connecting battery through the two windings of relay 1737 to the tip and ring conductors as previously described. In position 8 of sequence switch 1400 the tip conductor is connected to ground through resistances 1129 and 1128, winding of relay 1122, and the upper left contact of cam 1437, which resistances amount to approximately 7500 ohms, while the ring conductor is connected to ground through relay 1121. This represents a more severe non-operate condition than relay 1737 will ever be called upon to meet under service.

If relay 1737 does not operate, switch 1700 advances, connecting ground from the right contact of relay 1804, over conductor 1828, brush 1706 and terminals 18 to 21, next to the outermost right contact of relay 1710, conductor 1813, outer left contact of relay 1806, conductor 1817, sender selector brush 1528 and its corresponding contact, brush

1507 and its corresponding contact, middle left front contact of relay 1422, inner left front contact of relay 1118 and thence as previously traced through the windings of relays 502 and 503. Relays 502 and 503 operate in this circuit. The operation of relay 502 closes a circuit from battery through the winding of sequence switch magnet 1400, upper right contact of cam 1405, front contact of relay 502, lower right contact of cam 310, back contact of relay 511 to ground, advancing sequence switch 1400 to position 9.

If relay 1737 of the sender operates falsely under this condition, the switch 1700 does not advance, sequence switch 1400 is not advanced, and the test is blocked to sound an alarm. Lamp 1120 is lighted at this time to indicate the failure during test of coin refund. With sequence switch 1400 in position 9 relay 1402 operates in a circuit from battery through its right winding, upper left contact of cam 1403, front contact of relay 1414, left normal contact of key 1418, right back contact of relay 1407, lower right contact of cam 1429 to ground. The operation of relay 1402 closes the usual circuit for relay 1404 and the sender is restored to normal in the manner previously described. The operation of relay 1404 closes a circuit from battery, through the winding of sequence switch magnet 1400, lower left contact of cam 1405, inner right front contact of relay 1404, back contact of relay 1406 to ground advancing sequence switch 1400 to position 10. When the sender is returned to normal relays 1402 and 1404 release as previously described and relays 1438, 1421 and 1422 reoperate causing the operation of relays 1803, 1804, 1805, 1807 and 1705 as previously described. The sender is now given a test for coin return, the tip being grounded over the upper right contact of cam 1423, lower contacts of cam 1430, resistance 1128, winding of relay 1122, upper left contact of cam 1437 to ground, and the ring conductor over relay 1121. Since the fundamental ring conductor is open, coin return battery is supplied from the contact of relay 1723 of the sender and relays 1121 and 1122 operate. The operation of these two relays closes the circuit previously traced for relay 1118. The operation of relay 1118 closes a circuit from battery, through the winding of sequence switch magnet 1400, lower left contact of cam 1431, inner left front contact of relay 1118, left closed contact of key 1418, right back contact of relay 1407, lower right contact of cam 1428 to ground, advancing sequence switch 1400 to position 11.

In position 11 the tip and ring leads are connected together over the upper right contact of cam 1423, lower contacts of cam 1430, resistances 1128, and 1138 and the lower contact of cam 130

1424. Ground is connected through relay 1122 to a point between resistances 1128 and 1130. This condition simulates the condition existing when a second coin is deposited 5 and the receiver removed from the switch-hook to make a second call directly after the completion of a call. The sender connects the windings of relay 1737 to the tip and ring conductors as previously described.
- 10 It will be remembered that relay 1737 is a differential relay. Therefore since resistances 1130 and 1128 are of the same value, relay 1737 does not operate and the time measure circuit of Fig. 17 advances to connect ground to conductor 1817 and operates relay 502 as previously described. The operation of relay 502 again closes the circuit previously described for sequence switch 1400 and advances that sequence switch to 15 position 12. If relay 1737 operates falsely, this test is blocked also as previously described.
- 15 In position 12 of switch 1400, relay 1402 is again operated to operate relay 1404 and the sender restored and reselected. The operation of relay 1404 closes the previously traced circuit for sequence switch 1400 advancing that sequence switch to position 13. In position 13 the coin collect feature of 20 the sender is tested. In this position of sequence switch 1400, the tip conductor is extended through the inner left front contact of relay 1422, lower contact of cam 1423, upper contacts of cam 1444, winding 25 of polarized relay 1122, resistance 1128, upper left contact of cam 1437 to ground. It will be noted that the connection of relay 1122 at this time is reversed so that it will be responsive to positive battery on the tip 30 of the line. The ring conductor is connected through the outer left front contact of relay 1422, upper contact of cam 1424, winding of relay 1121 to ground. In this position of sequence switch 1400 ground is connected over the lower right contact of cam 1428, right back contact of relay 1407, left 35 closed contact of key 1418, front contact of relay 1414, lower contact of cam 1432 and the outer right front contact of relay 1422 to the fundamental ring conductor 1819 from whence it is extended as previously described to the winding of coin collect relay 1732. The operation of relay 1732 causes the sender to connect 110 volt positive battery to the line, operating relays 1122 and 1121. The operation of these relays causes the operation of relay 1118 as before. The operation of relay 1118 at this time closes a circuit from battery, winding 40 of relay 1117, lower left and upper right contacts of cam 1425, inner left front contact of relay 1118, left normal contact of key 1418, right back contact of relay 1407, upper right contact of cam 1428 to ground.

Relay 1117 locks over its right front contact, lower left contact of cam 1437 to ground. Having applied coin collect battery the sender advances opening the circuit of relays 1121 and 1122 and these relays release in turn releasing relay 1118. 65 When relay 1118 closes its back contact a circuit is completed from battery, through the winding of sequence switch magnet 1400, upper right contact of cam 1405, left front contact of relay 1117, left 70 back contact of relay 1118 to ground at the lower right contact of cam 1428. Sequence switch 1400 advances to position 14 opening the locking circuit of relay 1117. The advance of the sender connects the 75 windings of relay 1737 to the tip and ring conductors to test whether the coin has been collected.

In position 14 of sequence switch 1400 the ring conductor is opened and the tip conductor is connected over the lower contact of cam 1423, through resistance 1132, winding of relay 1122, resistance 1128, upper right contact of cam 1437, to ground. The windings of relay 1737 are obviously 80 unbalanced and relay 1737 operates. If relay 1737 fails to operate at this time the sender is advanced to connect ground over conductor 1817 to relay 502. When relay 502 operates it closes a circuit for relay 1117 85 which relay operates and blocks the test. If relay 1737 operates properly, as soon as interrupter 1435 closes its lower contact, sequence switch 1400 is advanced to position 15 in a circuit from battery, through the winding of magnet 1400, upper contact 90 of cam 1413, lower contact of interrupter 1435, left back contact of relay 1117, left back contact of relay 1118 to ground as previously described. Sequence switch 1400 95 is then advanced to position 16 as soon as interrupter 1435 closes its lower contact, in a circuit from battery, through its winding, lower right contact of cam 1413, upper contact of interrupter 1435 to ground. Sequence switch 1400 is then advanced to position 17 in the same manner as it was advanced to position 15 and to position 18 in the same circuit which advanced it to position 16. This gives a time interval sufficient for the sender to function and block the test circuit provided relay 1737 does not operate. As the switch leaves position 17 ground is disconnected from the winding 100 of relay 1438 at the upper right contact of cam 1449 and the sender is allowed to return to normal. Relay 1438 is released, in turn releasing relays 1421 and 1422. The sender selector switch 1540 is now advanced to the next sender as previously described 105 and all tests are made on this sender.

When making tests of coin senders for calls to local operators, district operators,

etc., for which tests class sequence switch 320 is set in positions 3 to 8, and which calls are usually free, relay 819 is not operated since the circuit traced for that relay is 5 open at cam 317 of switch 320 in these positions.

When it is desired to make only one of the multiple tests on each sender multi-test key 1101 is not operated and the route control switch 1300 and the numerical switch 10 are set by hand in the desired position.

Since these switches are set by hand, relays 322 and 1213 are not operated and the 15 relays associated with the registers are not operated. In this condition a substitute circuit is provided for operating relay 832 independent of the contacts of the register relays which circuit may be traced from battery, through the left winding of relay 20 832, upper contact of interrupter 833, front contact of relay 803, upper contact of cam 529, uppermost normal contact of key 1101, lower contacts of cam 528, left contacts of cam 822, left contacts of cam 1426, left 25 front contact of relay 1421, left back contact of relay 1404, left back contact of relay 1415, inner left operated contact of key 1401, left contact of relay 1427, right back contact of relay 1406, left back contact of relay 1407, 30 upper contact of cam 1409 to ground. The operation of relay 832 causes the advance of sequence switch 800 as previously described.

Since the circuit of the route control sequence switch magnet 1300 is through an 35 operated contact of key 1101 that switch is not advanced when check switch arrives in position 18. Likewise the circuit of relay 1317 is not closed and sequence switch 800 is advanced from position 12 to position 40 13 in a circuit from battery through the winding of that magnet, upper left contact of cam 807 inner upper normal contact of key 1101, upper contacts of cam 818, left contact of cam 203 to ground.

45 Sequence switch 1400 is advanced from position 4 to position 5, as soon as sequence switch 500 reaches position 17 in a circuit from battery, winding of sequence switch magnet 1400, upper left contact of cam 1431, upper normal contact of key 1115, left back contact of relay 1116, inner lower normal contact of key 1115, left back contact of relay 1116, middle lower normal contact of multi-test key 1101, lower left 50 contact of cam 529, uppermost normal contact of key 1101, lower right contact of cam 524 to ground. The testing device then proceeds with the coin test or immediately advances the sender and master switches depending upon whether or not the sender is 55 a coin sender.

When it is desired to test a sender for some particular number other than one of those provided for by the route control and

numerical switches, key 1105 is operated and 65 advances the route control switch to position 1, after which the register switches may be set manually in the positions desired for making the test.

70 Keys 1313 and 1316 are provided for imposing the maximum line condition or the minimum line condition respectively, for such tests as may be desired. With both keys normal, the route control switch varies the line conditions with the class of test. 75 Similarly, keys 1320 and 1321 are used to control the use of the high speed or low speed pulsing interrupter at will. The route control switch also varies the speed of pulses with the class of call. 80

If it is desired to test a coin sender for free calls other than those imposed by the route control switch in the cases above referred to, key 824 may be operated, preventing the operation of relay 819. The sender 85 is then tested as though it were a non-coin sender.

Repeat key 1115 serves to cause the test circuit to repeat a test on the same sender. As long as this key is held operated the test 90 will be repeated. If the key is operated and then released, relay 1103 is operated over the outer lower contact of key 1115, right contact of key 1133 to ground, locks to ground over the lower right contact if cam 1449, and remains locked in this circuit until the connector switch reaches position 1. The operation of repeat key 1115 opens the energizing circuit of magnet 1400 which is 95 closed in positions 4 and 6 over the upper left contact of cam 1431. The operation of relay 1103 opens the circuit of the sender selector magnet preventing the sender selector from advancing to the next sender. The operation of repeat key 1115 causes the 100 operation of relay 1402 to cause the restoration of the sender before the tests are repeated.

If it is desired to repeat the test of the 105 ability of the sender to control coin collection, etc., keys 1125 and 1115 are both closed completing a circuit from battery, through the winding of relay 1116, lower contact of key 1125, cross connecting rack 1319, outer left contact of relay 1303 to ground. Relay 1103 is also operated and locks as previously described. At the completion of a single test or of a group of tests, switch 1400 is in position 4 and a circuit is completed from battery, through the winding of magnet 1400, upper left contact of cam 1431, inner right front contact of relay 1116, and thence, if multi-test key 1101 is normal 115 over the left front contact of relay 1116, middle lower normal contact of key 1101, lower left contact of cam 529, uppermost normal contact of key 1101, to ground over the lower right contact of cam 524, or, if 120 125

multi-test key 1101 is operated, over the lower contact of cam 1324 left back contact of relay 1317, uppermost operated contact of key 1101 to ground, at the lower right contact of cam 524.

Sequence switch 1400 is advanced out of position 4 and proceeds with the coin test as previously described. Due to the operation of the repeat key and the repeat relay the 10 sender selector is not stepped to the next sender. At the completion of the coin test the sender is released and the complete test repeated on the same sender. The locking circuit of relay 1103 is opened when sequence switch 1400 passes through position 1, provided key 1115 has been released at that time, and only a single repetition of a test made. The operation of key 1125 with repeat key 1115 normal is ineffective on 20 tests.

Means have been provided to cause the repetition of tests a number of times on each sender. With keys 1133 and 1115 operated, single tests will be repeated on each sender 25 four times. This is accomplished by means of the group of relays 1448, 1450, 1451 and 1452. The operation of key 1115 opens the circuit for advancing sequence switch 1400 out of position 4. When sequence switch 30 800 passes through positions 3 to 5 a circuit is completed from battery, through the left winding of relay 1448, winding of relay 1452, left back contact of relay 1448, right operated contact of key 1133, inner lower 35 normal contact of multi-test key 1101, upper left contact of cam 838, to ground. Relay 1452 operates in this circuit, but relay 1448 does not. The operation of relay 1452 closes a locking circuit for itself from battery, through the right winding of relay 40 1448, left front contact of relay 1452, lower right contact of cam 1449 to ground. When sequence switch 800 leaves position 5 the energizing circuit of relay 1452 is opened and 45 relay 1448 energizes in the locking circuit of the two relays. When sequence switch 800 reaches position 3 on the second test, it connects ground over the left front contact of relay 1448, to the left winding of that relay, shunting the winding of relay 1452. Relay 1448 is held operated and relay 1452 releases. With relay 1448 operated and relay 1452 released a circuit is closed from battery, through the left winding of relay 50 1450, winding of relay 1451, left back contact of relay 1450, right front contact of relay 1448, left back contact of relay 1452 to ground at the lower right contact of cam 1449. Relay 1451 operates in this circuit but relay 1450 does not. Relay 1451 closes a locking circuit for itself similar to that closed for relay 1452. When sequence switch 800 leaves position 5 the circuit of relay 1448 is opened and relay 1448 releases.

Relay 1448 releasing, removes the ground from the right winding of relay 1450 and that relay operates in the locking circuit of relay 1451. When sequence switch 800 again reaches position 3 on the third test, a circuit is completed from battery through the left 65 winding of relay 1448, winding of relay 1449, left back contact of relay 1448 and thence to ground as previously traced. Relay 1452 operates and locks. When sequence switch 800 leaves position 5 relay 1448 operates in this locking circuit. When sequence switch 800 reaches position 3 on the fourth test, relay 1452 is released as before described. With relay 1452 released and relay 1448 operated ground is connected from the 70 lower right contact of cam 1449 over the left back contact of relay 1452, right front contact of relay 1448, left front contact of relay 1450 to the left winding of relay 1450. This shunts the circuit of relay 1451 and 75 that relay releases. The release of relay 1451 closes a circuit from battery through the winding of relay 1116, right front contact of relay 1450, left back contact of relay 1451, to ground on the lower right contact 80 of cam 1449. Relay 1116 operates and locks over its outer right front contact to ground at the lower right contact of cam 1449. When sequence switch 800 leaves position 5 the circuit of relay 1448 is opened and that 85 relay releases, in turn releasing relay 1450. The operation of relay 1116 closes the circuit previously described for advancing sequence switch 1400 from position 4 to 90 permit the advance of the test circuit to the next sender. The same test is then repeated 95 four times on the next sender.

When the last sender has been tested and the brushes of the last sender selector have been stepped to the first of the spare terminals, sequence switch 1400 is moved to 100 position 1. Relays 1402 and 1404 operate advancing sequence switch 1400 to position 105 2 and then release as previously described. The release of relay 1404 closes a circuit 110 from battery, through the right winding of relay 1406, first spare terminal of the last sender selector (the last few terminals of selector 1540 have been connected as though they were on the last sender selector for the 115 purpose of reducing the disclosure) brush 1531, master selector brush 1514 and its associated contact, right back contact of relay 1404, winding of relay 1438 right contact of key 1102, lower right contact of cam 1419 120 to ground. Relay 1406 operates and closes ground through its outer left front contact to the circuit above traced to hold that relay operated when sequence switch 1400 leaves position 17. Relay 1438 also operates and 125 closes a circuit for operating relay 1421. Relay 1406 also closes a circuit from battery, through the winding of sequence switch

magnet 1400 upper right contact of cam 1431, outer right front contact of relay 1406, outer left back contact of relay 1407 to ground at the upper contact of cam 1409. Sequence switch 1400 is advanced from position 17 to position 18 as previously described. The stepping magnet of the last sender selector, magnet 1532, is energized from battery, through the winding of that magnet, master selector brush 1513 and its associated contact, inner right front contact of relay 1406, left back contact of relay 1103, left contacts of cam 1412, master selector brushes 1503 and 1511 and their associated contacts to ground.

At the same time this ground is continued through the interrupter springs of the sender selector stepping magnet, brush 1502, and its associated contact, lower contact of cam 1417, resistance 1411 to battery shunting the circuit of relay 1410 which extends through the winding of that relay, over the lower left contact of cam 1412 to ground on master selector brush 1511. When the sender selector magnet energizes this shunt is opened and relay 1410 operates closing the circuit of sequence switch magnet 1400 and advancing that sequence switch to position 1 in the manner previously described. Sender selector 1540 is stepped to its next set of terminals.

In position 1 of sequence switch 1400, relays 1402 1404 again operate. The sequence switch 1400 is not energized since the circuit for so doing is open at the contact of relay 1406. Relay 1406 is held operated when sender selector 1540 steps to its second spare terminal in a circuit from battery, through its left winding and inner left contact, master selector brush 1502 and its associated contact, sender selector brush 1531 and the strapped spare terminals (second spare terminal to terminal No. 20) master selector brush 1514 and its associated contact, outer left front contact of relay 1406 to ground. Sender selector magnet 1532 is energized from battery through its winding and back contact, strapped spare terminals and thence over the locking circuit above traced for relay 1406 to ground. Magnet 1532 operates in this self-interrupting circuit to advance the sender selector 1540 to terminal 21. When the sender selector moves off terminal 20, the locking circuit of relay 1406 is opened and that relay releases closing a circuit for sequence switch magnet 1400, whereupon the sequence switch is advanced to position 4 as previously described. When the sender selector reaches terminal 21 a circuit is closed for relay 1427 from battery, winding of relay 1427, No. 21 terminal and brush 1531, master selector brush 1514 and its associated terminal, right back contact of relay 1404, winding of relay 1438 right contact of key 1102, lower right contact of cam 1419 to ground.

Relay 1427 operates and locks to ground at the upper contact of cam 1409. Relay 1438 operates in turn operating relay 1421 and 1422. The operation of relay 1427 closes a circuit through signal lamp 1434 indicating that all of the group of senders have been tested. The operation of relay 1427 also opens the circuit for advancing sequence switch 800 from position 1. If the test man does not notice the lighting of lamp 1434 before the time measure switch 1100 has completed its operation the sounding of bell 1126 will call his attention thereto. When the test man observes the lighting of lamp 1434, he operates key 1433, extinguishing the lamp and closing a circuit for relay 1407 from battery, through the right winding of that relay, left closed contact of cam 1433, outer right contact of relay 1427 to ground. Relay 1407 operates and locks through its left winding to ground at cam 1409. A circuit is closed for relay 1410 from battery, through resistance 1411, winding of that relay, right contact of cam 1412 to ground over the outer left front contact of relay 1407. The energizing circuit for master selector stepping magnets 1501 and 1512 are also completed, together with the circuits in shunt of relay 1410 as previously described. Master selectors 1500 and 1510 are stepped to their first spare contacts and sequence switch 1400 advances to position 7. Master selector 1500 is stepped back to normal in a self-interrupting circuit through brush 1508 and master selector 1510 is stepped back to normal in a self-interrupting circuit through brush 1511. Sequence switch 1400 is advanced from position 7 to position 17 as previously described. It is then advanced to position 18 in a circuit through its winding, lower right contact of cam 1431, normal contact of master selector brush 1511 to ground.

In position 18 relay 1410 and sender selector magnet 1532 are energized and the sender selector restored to normal after which sequence switch 1400 restores to normal. If start key 1401 has been restored at this time the system will remain at rest. If the key is still operated the circuits for relays 1402 and 1404 are closed and the cycle of operations repeated.

What is claimed is:

1. In a telephone exchange system in which connections are established under the control of a central office sending device said sending device having means operative on the deposit of a coin to permit the completion of a connection and on the non-deposit of a coin to prevent the completion of a connection, a testing device for simulating the initiation and extension of a connection under

the control of said sending device, and means in said testing device for checking the accuracy of the operation of said sending device in response to various coin conditions.

2. In a telephone exchange system in which connections are established under the control of a central office sending device, said sending device having means operative on the deposit of a coin to permit the completion of a connection and on the non-deposit of a coin to prevent the completion of a connection, a testing device for simulating the initiation and extension of a connection under the control of said sending device, including means for simulating the non-deposit of a coin, and means responsive to the failure of the sender to prevent the extension of the connection to prevent the completion of the test.

3. In a telephone exchange system in which connections are established under the control of a central office sending device, said sending device having means operative on the deposit of a coin to permit the completion of a connection and on the non-deposit of a coin to prevent the completion of a connection, a testing device for simulating the initiation and extension of a connection under the control of said sending device, including means for simulating unstandard coin conditions in response to which the sender operates to arrest the extension of a connection, and means responsive to such operation of the sender to cause the testing device to simulate standard coin conditions to permit the completion of the test.

4. In a telephone exchange system in which connections are established under the control of a central office sending device, said sending device having means operative on the deposit of a coin to permit the completion of a connection and on the non-deposit of a coin to prevent the completion of a connection, a testing device having means for simulating the initiation and extension of a connection under the control of said sending device, including means for simulating the non-deposit of a coin, and means responsive to the action of the sender in arresting the extension of the connection to simulate the deposit of a coin to permit the completion of the test.

5. In a telephone exchange system in which connections are established under the control of a central office sending device, said sending device having means operative on the deposit of a coin to permit the completion of a connection and means responsive to unstandard conditions to operate a signal at an operator's position and to prevent the completion of the connection, a testing device having means for simulating the initiation and extension of a connection under

the control of said sending device, means for simulating a trouble condition at a subscriber's substation to cause said signal operating means to function and means for retiring said signal and permitting the completion of said test.

6. In a telephone exchange system in which connections are established under the control of a central office sending device, said sending device having means operative on the deposit of a coin to permit the completion of a connection and other means for preventing the completion of a connection if the subscriber's line is in an unstandard condition, a testing device having means for simulating the initiation and extension of a connection under the control of said sending device including means for simulating the non-deposit of a coin to bring said first mentioned means into operation, means for subsequently simulating a trouble condition on a subscriber's line to bring said second means into operation and means responsive to the inaccurate functioning of said second means to prevent the completion of the test.

7. In a telephone exchange system in which connections are established under the control of a central office sending device, said sending device comprising a relay, means for connecting said relay to a subscriber's line, means for operating said relay to permit the completion of a connection if a coin has been deposited at the subscriber's substation, a second relay, means responsive to the operation of said first relay for connecting said second relay to said line, means for operating said second relay to prevent the completion of a connection and to operate a signal at an operator's position if a trouble condition exists on said line, a testing device having means for simulating the initiation and extension of a connection under the control of said sending device, including means for simulating the deposit of a coin to cause the operation of said first relay for connecting said second relay with said testing device, means for thereupon simulating conditions at the subscriber's substation such as to operate, release and energize but not operate said second relay and means operative in response to the correct functioning of said second relay to permit the completion of the test.

8. In a telephone exchange system in which connections are established under the control of a central office sending device, said sending device comprising a relay, means for connecting said relay to a subscriber's line, means for operating said relay to permit the completion of a connection if a coin has been deposited at the subscriber's substation, a second relay, means responsive to the operation of said first relay for connecting said second relay to said line, means for operating said second relay to prevent

- the completion of a connection and to operate a signal at an operator's position if a trouble condition exists on said line, a testing device having means for simulating the initiation and extension of a connection under the control of said sending device, including means for simulating the deposit of a coin to cause the operation of said first relay for connecting said second relay with the testing device, means for thereupon simulating conditions at a subscriber's substation such as to operate, release and energize but not operate said second relay, and means operative in response to the inaccurate functioning of the second relay to prevent the completion of the test and to sound an alarm.
13. In a telephone exchange system, in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device, means for repeatedly releasing and subsequently reconnecting with a particular sending device, means for causing the operation of said refund or collecting means at each reconnection with said sending device and means for simulating a different coin condition for the line testing operation of the sender taking place in connection with each operation of the collecting or refunding means.
14. In a telephone exchange system, in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device having means for simulating various coin conditions, means for repeatedly releasing and subsequently reconnecting with a particular sending device, means for causing the operation of said refunding or collecting means at each reconnection of the sending device, means for simulating a different coin condition for the line testing operation of the sender in connection with each operation of said refunding or collecting means and means responsive to the correct functioning of said line testing means of the sender to cause the continued operation of said testing device.
15. In a telephone exchange system, in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device having means for simulating various coin conditions, means for repeatedly releasing and subsequently reconnecting with a particular sending device, means for causing the operation of said refunding or collecting means at each reconnection of the sending device, means for simulating a different coin condition for the line testing operation of the sender in connection with each operation of said refunding or collecting means and means responsive to the correct functioning of said line testing means of the sender to cause the continued operation of said testing device.
16. A sending device to be tested having means controlled by the deposit of a coin at a subscriber's substation, and means for collecting or refunding said coin, a testing device having means for simulating the initiation and extension of a call under the control of said sending device to check the accuracy with which said sending device functions, means for subsequently testing the ability of the sender to collect or refund a coin, and means for causing said testing device to repeat said tests on the sending device.
17. A sending device to be tested having means controlled by the deposit of a coin at a subscriber's substation, and means for collecting or refunding said coin, a testing device, means in said testing device for checking the ability of the sender to control the extension of a call, means for testing the ability of the sender to collect or refund a coin, means for causing said testing device to repeat said first test and means for causing said testing device to repeat both said tests.
18. In a telephone exchange system in which connections are established under the control of a central office sending device, a testing device, means in said testing device for successively connecting with each of said senders, means for successively checking the ability of each sender to control the extension of a particular connection and means for checking the ability of a sender to extend said connection a plurality of times before checking the ability of the next sender to extend said connection.
19. In a telephone exchange system in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device, means for repeatedly releas-

- sending device; means for simulating a different coin condition for the line testing operation of the sender in connection with each operation of said refunding or collecting means and means responsive to the inaccurate functioning of said line testing means of the sender prevent the further operation of said testing device and to sound an alarm.
16. In a telephone exchange system, in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device having means for simulating various coin conditions, means for repeatedly releasing and subsequently reconnecting with a particular sending device, means for causing the operation of said refunding or collecting means at each reconnection with said sending device, means for simulating a different coin condition for the line testing operation of the sender in connection with each operation of said refunding or collecting means, and means responsive to the accurate operation of said line testing means of the sender in response to the coin condition imposed by the testing device to cause the release of the sender.
17. In a telephone exchange system in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device having means for simulating various coin conditions, means for repeatedly releasing and subsequently reconnecting with a particular sending device, means for causing the operation of said refunding or collecting means at each reconnection with said sending device, means for simulating a different coin condition for the line testing operation of the sender in connection with each operation of said refunding or collecting means, means responsive to the accurate operation of said line testing means of the sender in connection with the coin condition imposed by the testing device subsequent to coin refund to cause the testing device to release and reconnect with said sender.
18. In a telephone exchange system in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device having means for simulating various coin conditions, means for repeatedly releasing and subsequently reconnecting with a particular sending device, means for causing the operation of said refunding or collecting means at each reconnection with said sending device, means for simulating a different coin condition for the line testing operation of the sender in connection with each operation of said refunding or collecting means, means responsive to the accurate operation of said line testing means of the sender in response to the coin condition imposed by the testing device to cause the testing device to release and reconnect with said sender.
19. In a telephone exchange system in which connections are established under the control of a central office sending device, said sending device having means for collecting or refunding a coin deposited at a subscriber's substation, for testing the line of said substation to determine whether said refund or collection has been made and for thereupon displaying a signal before an operator if said coin is still present, a testing device, means for simulating the presence of a coin, means for causing the operation of said refunding means, means responsive to the operation of said refunding means to cause the simulation of the absence of a coin to the line testing means of the sender, means responsive to the operation of said line testing means of the sender to cause said testing device to dismiss said sender and reconnect therewith, means for again simulating the presence of a coin and for causing the operation of said refunding means, means responsive to the operation of said refunding means to cause the simulation of the presence of a coin in connection with a second call when said line testing means of the sender functions, means responsive to the correct operation of said line testing means of the sender to cause said testing device to again dismiss and reconnect with said sender, means for causing the operation of said coin collect means, means responsive to the operation of said coin collect means to simulate the continued presence of a coin to cause the line testing means of the sender to operate, and means responsive to the operation of said line testing means to permit the completion of the test.
- In witness whereof, we hereunto subscribe our names this 25th day of September A. D., 1924.
- WILLIAM L. DODGE,
JOHN B. RETALLACK.
